[57] ABSTRACT

Carry transfer mechanism for mechanical registers of calculating machines, including such mechanism capable of performing two primary transfers in a single registration. Two primary transfers may occur, when a units and tens of an integrated partial product are registered in a single order of a register that already indicated a number, for example the units amount (9) of one order may be integrated with a tens amount (8) of the next lower order and in one motion the integrated amount (17) may be entered into one register order that stands at more than 3 (4 for example), and, for the register to indicate (9+8+4), the one register order is rotated twice past primary transfer position and the next higher order of the register unit must be advanced twice in one registration operation. A mechanism cooperating with the above mechanism for completing simultaneously any consecutive transfers that may not normally be complete at the end of a registration operation. Simultaneous transfer mechanism for operating outboard orders of a carriage borne register. Simultaneous transfer mechanism for a counter that may also register quotients and multipliers.

CARRY MECHANISMS FOR CALCULATING MACHINES

This is a continuation of application Ser. No. 168,595, filed Jan. 22, 1962, now abandoned, which is a continuation of application, Ser. No. 69,227, filed Nov. 14, 1960 (now abandoned), which in turn was a division of Ser. No. 194,273, filed Nov. 6, 1950, now U.S. Pat. No. 2,969,177 issued Jan. 24, 1961.

This invention relates to improvements in calculating machines and the mechanisms and construction thereof.

An object of the invention is to provide a novel and improved calculating mechanism in which there is means for effecting simultaneous actuation of a series of adjacent orders of crawl carry means when the associated accumulators each indicates "9" in additive operations, or indicates "0" in subtractive operations, and the lowest of such orders of accumulators is rotated through a tens carry position.

Another object of the invention is to provide in a calculating machine comprising ordinal accumulators and resiliently biased carry means for each accumulator triggerable responsive to rotation of the adjacent lower order accumulator through tens carry position, so that carry operations in a series of accumulators will be performed consecutively in crawl-like manner, a simultaneous carry triggering means for effecting triggering at the same time in a series of orders of carry means in which triggering is to occur and has not yet been performed in the consecutive operations.

Another object of the invention is to provide simultaneous carry means in a calculating machine having a plurality of ordinal accumulators, ordinal accumulator actuators and a tens carry device for each actuator for advancing the actuator for a tens carry in the associated accumulator and movably responsive to rotation of the adjacent lower order accumulator through tens carry position, the simultaneous carry means comprising motivating means common to all said carry devices, ordinal sensing means all operable together for sensing the associated accumulators standing at pre-carry position, adjacent the tens carry position, an actuating means for and engaging each carry device for operating its carry device when the carry device is at rest position upon movement of the actuating means, the actuating means being engageable with the motivating means only at the operated position of the carry device and being movable in advance of the carry device in operated position and a latch means on each actuating means movably responsive to the related sensing means when the associated accumulator stands at pre-carry position for inter-coupling with the adjacent lower order actuating means, so that all actuating means inter-coupled in series with the highest order actuating means engaged with the motivating means are all moved together for effecting tens carry in the associated accumulators when the motivating-means-engaged highest order actuating means is moved by the motivating means.

Another object of the invention is to provide a novel and improved calculating mechanism in which there is carry means for accumulators on an ordinally shiftable carriage and being outboard relative to the main actuating and carry mechanism of the machine, which carry means carried by the carriage operates the first outboard order accumulator for a tens carry when the adjacent highest inboard order accumulator is rotated through tens carry position, and which operates all higher order accumulators in series with the first outboard accumulator for tens carry, when all the accumulators in series and the first outboard accumulator all indicate "9" in additive operations, or indicate "0" in subtractive operations, and the highest order inboard accumulator is rotated through tens carry position.

Another object of the invention is to provide a novel and improved carry device for outboard orders of a product register on an ordinally shiftable carriage in a calculating machine including a cyclically operable motivating means and a multiplying device operable by the motivating means for obtaining and entering a multidigit product in the inboard orders of the register therefor during a predetermined portion of each revolution of the motivating means, the carry device

being operable by the motivating means in each revolution subsequent to actuation of the multiplying means, and being constructed so as to perform tens carry actuation in the first outboard order when the highest inboard order is rotated through tens carry position, and to actuate all higher orders of said register in series with the first outboard order when the orders in series and the first outboard order each indicates "9" in the additive operations, or indicates "0" in subtractive operations, and the highest inboard order of the register is rotated through tens carry position.

A further object of the invention is to provide a novel and improved carry device for counters on an ordinally traversable carriage, the first inboard counter being operable by an actuator therefor, and all other adjacent higher order inboard counters being associated with the carry device which actuates the second inboard counter for indicating a tens carry when the first inboard counter is rotated through tens carry position, and which carry device operates all inboard counters in series with the second inboard counter simultaneously with the second inboard counter when the second inboard counter and each counter of the series indicates "9" in additive operations, or indicates "0" in subtractive operations, and the first inboard counter is rotated through tens carry position.

Still another object of the invention is to provide a novel and improved carry mechanism and assembly, which is so constructed as to be usable, and adaptable for use in a variety of different types of counting and calculating devices utilizing item counters.

Another object of the invention is to provide a novel and improved carry device for a plurality of ordinal item counters on an ordinally traversable carriage in a calculating machine including a cyclically operable motivating means and computing device operable by the motivating means for entering a digit value in the first inboard counter during a predetermined portion of each revolution of the motivating means, the carry device being actuatable by the motivating means in each revolution subsequent to actuation of the computing device, and being so constructed as to perform tens carry actuation of the second inboard counter when the first inboard counter is rotated through tens carry position, and to perform tens carry actuation of each higher order inboard counter in series with the second inboard counter simultaneously with the carry actuation of the second inboard counter when each counter of the series and the second inboard counter indicates "9" in additive operations, or "0" in subtractive operations, and the first inboard counter is rotated through tens carry position.

The foregoing and various other objects, advantages and features of the invention will become more apparent and more readily understood upon reference to the following description. It will be apparent, however, that those skilled in the art will be enabled to apply the teachings of the disclosure to various modifications as intended to be covered by the scope of the appended claims. The description is directed to a preferred exemplary embodiment of the invention illustrated in the accompanying drawings forming a part hereof, in which:

FIG. 1 is a top face view of a calculating machine embodying the invention, the carriage being shown in fragment in its leftmost position;

FIG. 2 is a fragmentary top face view similar to that of FIG. 1, but showing the carriage shifted all the way to the right;

FIG. 3 is a fragmentary top plan view of the machine and carriage frame members;

FIG. 4 is a fragmentary sectioned view showing principally the multiplying power unit and the drive shaft, and schematically showing, among others, two other power units on the drive shaft, the motor for turning the drive shaft and two differentials for connecting the power units with the drive shaft for being actuated thereby;

FIG. 5 is a fragmentary detailed top view of a transverse frame member;

FIG. 6 is a fragmentary left sectional elevational view taken substantially on plane 6-6 of FIG. 1, showing principally the keyboard frame members and the anti-frictional support means for the carriage, and omitting other parts for clarity;

FIG. 7 is a fragmentary perspective view showing principally the centralizing rods for the multiplication plates and for the multiplier set-up means;

FIG. 8 is a right side view showing principally the stop-start means for the multiplying power unit;

FIG. 9 is a right side elevation taken substantially on line 9-9 of FIG. 1, showing principally an ordinal group of multiplication plates, units and tens sensing means therefor, the dial actuating means of the respective order connected with the units sensing means also of that order, and omitting other parts for clarity;

FIG. 10 is a fragmentary detail view of the 0, 1, 2, 3 and 4 value multiplication plates, showing principally the partial product stops thereon;

FIG. 11 is a fragmentary detail view of the 5, 6, 7, 8 and 9 value multiplication plates, showing principally the partial product stops thereon;

FIG. 12 is a fragmentary left side view showing principally the left member of the support unit for the multiplier entry mechanism and the product entry and carry mechanisms, and showing the detent means for the support unit, all in normal rest position;

FIG. 13 is a fragmentary, partly broken out, right side view showing principally the right member of the support unit in rest position, the cam means for elevating the support unit, and also showing the subtractive operations control means;

FIG. 14 is a fragmentary, partly broken out, left side view showing principally the left member of the support unit in elevated position, and also showing the support unit detent means and linkages of the subtractive operations control;

FIG. 15 is a fragmentary perspective view showing principally parts of the product entry mechanism including the partial product integrating means of one order connected with the units sensing means of that order and with the tens sensing means of the adjacent lower order, and also showing the actuating bail means common to all orders of the entry mechanism for actuating the same;

FIG. 16 is a fragmentary right side view of the cam and cam follower means for motivating the actuating bail means of FIG. 15;

FIG. 17 is a fragmentary left side view showing principally a portion of the rack means of the product entry mechanism of an order, and showing elements of the carry mechanism on the rack means, all in rest position;

FIG. 18 is a fragmentary left side view showing principally a portion of the rack means and the carry elements of FIG. 17 in operated position for a first carry;

FIG. 19 is a fragmentary left side view showing principally a portion of the rack means and the carry elements of FIG. 18 in operated position for a second carry, subsequent to a first carry in the same cycle of operations;

FIG. 20 is a fragmentary right side view showing the cam, cam follower and linkage means for actuating, among others, the subtractive operation control means shown in FIG. 13, and the resetting means, shown in FIG. 55, for the multiplier register carry mechanism;

FIG. 21 is a fragmentary perspective view showing principally the dial actuated tripping means of an order for triggering the main carry mechanism of FIG. 17, in the adjacent higher order, and for rendering effective the first outward order of the carry mechanism for outward orders of the product register;

FIG. 22 is a fragmentary left side elevation showing elements of the linkage between the tripping means of FIG. 21 of one order and the carry mechanism of FIG. 17 of the adjacent higher order;

FIG. 23 is a fragmentary perspective view showing principally the multiplying power unit actuated elements for effecting simultaneous carry and sensing therefor, and for effecting return of the support unit to rest position;

FIG. 24 is a left side elevation of elements of the simultaneous carry triggering mechanism of an order;

FIG. 25 is a fragmentary perspective view showing principally the means for connecting together adjacent orders of the simultaneous carry triggering mechanism;

FIG. 26 is a fragmentary front elevation of several elements of the simultaneous carry sensing mechanism of an order shown in FIG. 28;

FIG. 27 is a side elevation of several elements of the simultaneous carry sensing mechanism of an order shown in FIG. 28;

FIG. 28 is a left side elevation of elements of the simultaneous carry sensing mechanism of an order;

FIG. 29 is a left side elevation showing principally the latch means for engaging the first outward order carry mechanism with the actuating rod therefor;

FIG. 30 is a left side elevation of the dial actuator of one order of the outward carry mechanism, the actuator being shown in position for additive operations;

FIG. 31 shows the dial actuator of FIG. 30 in position for subtractive operations;

FIG. 32 is a fragmentary perspective view showing elements of the subtractive operation mechanism for shifting all orders of dial actuators from additive to subtractive position;

FIG. 33 is a fragmentary left side elevation showing principally the latch blocking means for latches that are moved in-board, and also showing the means for connecting together adjacent orders of the outward carry mechanism;

FIG. 34 is a fragmentary left side elevation of carry sensing means for actuating the connecting means of FIG. 33 for, at times, interconnecting the respective adjacent orders of the outward carry mechanism;

FIG. 35 is a fragmentary perspective view showing several orders of the sensing means in FIG. 34 and the interconnecting means of FIG. 33 controlled thereby;

FIG. 36 is a fragmentary exploded perspective view showing principally the actuating mechanism for programmed operation of the dial actuators of FIG. 30 and of the sensing means of FIG. 34, and also showing the centralizer for the actuating mechanism;

FIG. 37 is a left side elevation of several elements of the actuating mechanism shown in FIG. 36;

FIG. 38 is a fragmentary left side elevation of several parts of the actuating mechanism shown in FIG. 36;

FIG. 39 is a fragmentary left side elevation of several elements of the subtractive operation mechanism for outward orders shown in FIG. 32, and the engagement therewith of the subtractive operations control means shown in FIG. 14;

FIG. 40 is a right side elevation showing principally the multiplying power unit actuated linkage means for operating the actuating mechanism of FIG. 36;

FIG. 41 is a fragmentary longitudinally sectioned view of a telescoping shaft means for transmitting, among others, power from the linkage means of FIG. 40 in the main body of the machine to the carriage borne actuating mechanism of FIG. 36;

FIG. 42 is a fragmentary longitudinally sectioned view of a telescoping shaft means for transmitting, among others, power from the subtractive operations control means of FIG. 14 to the carriage borne subtractive operation mechanism of FIGS. 32 and 39;

FIG. 43 is a fragmentary right side elevation showing principally the digit control for the multiplier entry mechanism and the non-entry control means therefor;

FIG. 44 is a fragmentary right side elevation of the multiplier entry mechanism and of the subtractive operation control therefor;

FIG. 45 is a partly broken out fragmentary right side elevation of the dial actuated triggering means for the first order of the multiplier register carry mechanism, and shows, among others, the support unit in elevated position;

FIG. 46 is a fragmentary right side elevation showing the dial actuator of one order of the multiplier carry mechanism, and also showing parts of the motivating means and of the subtractive control means for the dial actuator;

FIG. 47 is a right side elevation showing principally an element of the triggering means of FIG. 45 disengaged from the dial and carry mechanisms;

FIG. 48 is a perspective view showing a multiplier dial in one preferred form;

FIG. 49 is a right side elevation of the yieldably constrained add-subtract position means for the subtractive operation control of the multiplier register carry mechanism;

FIG. 50 is a side elevation showing principally the dial actuator and the carry sensing means of an order of the multiplier register carry mechanism and also showing the latch element for coupling the dial actuator with the motivating means therefor;

FIG. 51 is a right side elevation showing principally the sensing means of FIG. 50;

FIG. 52 is a right side elevation showing elements of the sensing means of FIG. 51 and of the actuating means therefor;

FIG. 53 is a right side elevation showing elements of the sensing means of FIG. 51 and showing the detent of the adjacent order operated thereby;

FIG. 54 is a fragmentary front elevation of several orders of the latch shown in FIG. 50, and showing principally the lug of each for engagement of successive latches for, at times, blocking carry in certain orders;

FIG. 55 is a left side elevation showing principally the support unit actuated motivating means for the multiplier register carry mechanism and also showing the multiplying power unit actuated elements for effecting resetting operations in the carry mechanism;

FIG. 56 illustrates several elements of the motivating means shown in FIG. 55.

The specification is comprised of the following topics:

1. General Description.
2. Multiplying Power Unit.
3. Multiplication Elements.
4. Support Unit For Register Actuating Mechanisms.
5. Product Register Actuating And Carry Mechanisms.
6. Means for Effecting Carry.
7. Means For Effecting Simultaneous Carry.
8. Carry Mechanism For Outboard Register Orders.
9. Actuating And Subtractive Operation Setting Means For Outboard Carry Mechanism.
10. Telescoping Shaft Means.
11. Multiplier Register Entry Mechanism.
12. Multiplier Register Carry Mechanism.

Reference to direction in the specification, such as "forward," "rearward," "rightward," "leftward," etc. is made with respect to the machine as viewed in FIG. 1, unless otherwise specified. A dial or numeral wheel standing at "9" in additive operations and at "0" in subtractive operations may be referred to as standing at "pre-carry." Also, a carriage borne dial may be referred to as an "inboard" dial — one that is in an ordinal position relative to an order of the main entry and carry mechanism for being engageable by the particular order of the mechanism — and as an "outboard" dial — one that is in an ordinal position displaced from all ordinal positions relative to the entry and carry mechanism.

1. GENERAL DESCRIPTION

The machine in which the present invention is embodied is disclosed in copending application, Ser. No. 69,227, filed Nov. 14, 1960, for Carry Mechanisms For Calculating Machines of which the present application is a continuation, and is disclosed in detail in the parent application, Ser. No. 194,273, filed Nov. 6, 1950, by William S. Gubelmann, now U.S. Pat. No. 2,969,177 to which reference may be had for a complete disclosure not otherwise repeated herein. A brief summary of the machine and its operations, however, is presented herewith in order to facilitate understanding of the invention and its interaction with various mechanisms of the machine.

The machine shown in FIG. 1 embodies predetermined partial product and quotient representations in a multiplying and dividing mechanism respectively, a shiftable carriage 1 which carries counter and accumulator registers 2 and 3 respectively; several banks of keys 4 for setting up factors in various arithmetical calculations; a bank of multiplier keys 5, each of which for values 1 to 9 inclusive, serves to initiate a multiplying cycle of operations; initiating or cycling keys for addition, subtraction, division and carriage shift; a tabulating

mechanism, and an automatically powered driving mechanism comprising three main actuating units, each individual to and for motivating a different one of the multiplying, dividing and carriage shifting mechanisms. Hereinafter, each main actuating unit is referred respectively as the multiplying, dividing and carriage power unit.

Results and factors of the various computations are exhibited in ordinarily disposed dials of registers 2, 3 and 6 as follows: Register 2, carried by the carriage, can indicate the multiplier, quotient, or the number of items in addition or subtraction as the case may be and, alternatively, the complement of any of the foregoing. Register 3, also carried by the carriage, can indicate the product, dividend, sum, difference, or such complements thereof as are desired. Stationary register 6 shows for easy reading a currently set-up factor on keys 4. Each register comprises ordinarily disposed dials or number wheels as at 7, 8 and 9, and the digits 0-9 about the periphery of each being visible through suitable apertures on the respective overlying cover plates.

This machine, commonly known as a "four rules calculator," performs the arithmetical calculations of addition, subtraction, multiplication and division automatically. Multiplication is direct, as distinguished from repeated addition, in that

25 the machine multiplies in a manner closely analogous to the operational methods used in mental computations. Plate means bearing representations of products for digits 0 to 9 times 1 to 9 are provided for selection and setup respectively in accordance with the separate digits of the multiplicand and 30 each digit of the multiplier. The partial products thus obtained are integrated into the final product. Depression of a key 4, value 1 to 9, in a bank selects the plate bearing products of that value times the digits 1 to 9. Each multiplier key 5 for values 1 to 9 serves as an initiatory control for effecting operation 35 of the computing mechanism, and exercises a control over the computing mechanism for setting up the multiplicand digit selected plates according to the value of the depressed multiplier key, so that the pertinent partial product on each plate is at a sensing position. A cycle of multiplying operations 40 also includes the operation of automatically initiating an ordinal shift of the carriage. Depression of the "0" value key 5 initiates an ordinal shift of the carriage without first having to excite the computing mechanism.

45 Selectively operable keys 10, 11 and 12 are provided for controlling the direction of shift and non-shift of the carriage, as for multiplication. With key 10 in depressed position, the automatic ordinal shift of the carriage will be leftward, but with key 12 in depressed position instead, the ordinal shift of the carriage will be rightward, as indicated by the arrows on these keys. In each instance, the carriage will shift in the opposite direction to a preselected start position with the use of carriage return key 13. With the non-shift key 11 in depressed position, the automatically operated shift initiating means is 50 normally disabled.

55 The tabulating mechanism stops the carriage at an ordinal position by directly blocking operation of the carriage traversing mechanism. The tabulating mechanism is brought into operation automatically each time the carriage shifts to either end position. A similar carriage stopping operation of the tabulating mechanism will also occur at an intermediate ordinal position, as with the use of key 13, provided that preselection of that position is made by depression of an appropriate one of the tabulator keys 14, which are self-lockable and are releasable upon depression of a "tab clear" key 15 at either end.

70 60 Addition and subtraction calculations are performed by automatically treating the factors thereof as multiplicands and multiplying the factors by "1." Add key 16 and subtract key 17 are in effect "1" value multiplier keys, but the cycle of operations instituted thereby preclude the operation of initiating a carriage shift cycle. The product thus obtained of a subtrahend is registered subtractively by the dials of the register therefor. Selective means is also provided for effecting subtractive registration of other products.

Heretofore, several different principles have been utilized for obtaining quotients automatically, including repeated subtraction and logarithmic processes. In this machine, division is accomplished directly by structural elements in a manner somewhat analogous to the method corresponding to the well known mental procedure in "long division." The mechanism used for a calculation in division includes representations on plate elements of predetermined quotient values for dividends from 0 to 99 divided by divisors 1 to 9, means for selecting a plate element and setting up the same, and means for deriving the trial quotient value from the involved representation, and the dividing mechanism also makes use of the multiplying mechanism. This means that when a dividend has been set up in register 3 and a divisor has been set up in keys 4, upon depression of a divide key, 18 or 19, the machine automatically selects a quotient value in accordance with the highest order of the divisor and the highest order of the dividend in the first cycle of operations, and the two highest orders of the dividend remainder in each successive cycle of operations. Each selected value is the "trial quotient" value which is then entered automatically into multiplication with the divisor, and the resulting product is subtracted from the dividend in register 3. Key 18 or 19 may be depressed only when the machine is properly set up for a division computation. The machine is prepared for such a computation as follows:

The carriage is shifted to its rightmost position, as illustrated in FIG. 2, preferably by the depression of extreme shift key 20, FIG. 1. At this rightmost position of the carriage, FIG. 2, the 19th dial 8 is then in alignment with the leftmost bank of keys 4 to receive a registration therefrom. The dividend is then set up in the multiplicand selecting mechanism by keys 4, preferably with the highest order of the dividend in the leftmost bank of keys 4. With the use of add key 16 (FIG. 1) the dividend is entered into register 3 with the highest order appearing in the 19th order dial 8, FIG. 2, the lower of the two highest inboard dials. Non-entry key 21 (FIG. 1) is depressed simultaneously with add key 16 whereby operation of the multiplier entry mechanism is blocked and entry of the item "1" in register 2 is prevented. The divisor is then set up in the multiplicand selecting mechanism by keys 4, with the highest order real digit, i.e., a digit other than "0," in the leftmost bank. In addition to making a selection of relative partial products, the depressed key 4 in the leftmost bank also effects selection in the dividing mechanism of the quotient bearing plate element relative to the value of that key.

Depression of either divide key is normally blocked by key-lock means which are rendered ineffective only when both the carriage is in its rightmost position and a real digit key 4 is depressed in the leftmost bank. The key-lock mechanism also includes, among others, means for holding a cycling key in operated position until the final phase of the operations instituted thereby are completed, and for preventing actuation of a cycling key while another cycling key is in operated position, and while a factor key 4 is partially depressed.

Operation of either key 18 or 19 excites a mechanism which conditions the machine (without upsetting current operational setups that may be incongruous with requirements for division) for subtractive entry of products and for sequential operations of the dividing, multiplying and carriage traversing mechanisms, the latter to shift the carriage leftward. The conditioning mechanism also initiates the first cycle of operations of the dividing mechanism for the division process. With the use of key 19, the conditioning mechanism also renders the tabulating mechanism effective to cause termination of the division process upon registration of a predetermined number of quotient digits. First, however, the tabulating mechanism must be preset by depression of that tabulator key 14 which corresponds with the number of digits desired. With the use of key 18, whether or not a tabulator key selection is made, or with the use of key 19 when a selection is not made, the tabulating mechanism will cause termination of the process only when the ordinal capacity of the machine is reached.

In division processes the problem is said to be "solved" whenever the dividend is eliminated, i. e., reduced to "0." Sensing means, one for each of the inboard dials 8 in register 3, are all movable together, and movement of the sensing means is obstructed when a dial 8 is displaced from "0" position, indicating a remainder. Accordingly, turning of all the dials 8 to "0" position enables the sensing means to move, whereupon the sensing means effects termination of the division process automatically, there being no remainder and no reason for continuing the operations. Both the eliminated dividend sensing means and the tabulating mechanism motivate a mechanism which terminates the division process after the final true quotient digit is registered in register 2.

Selection of a trial quotient value is made from representations of quotient values provided for dividend numbers ranging from 0 to 99 divided by divisor digits 1 to 9, both inclusive. The trial quotient first obtained may be an "overestimation." In that case the mechanism automatically reduces the trial quotient by "1" and makes one or more further attempts to obtain the true quotient. When the true quotient, a single digit, is so obtained, it is registered in register 2. Failures to obtain the true quotient are evidenced by an overdraft from the dividend, which is automatically cancelled out by adding back into register 3 the amount subtracted therefrom, i.e., the product of the divisor times the trial quotient which proved to be too large. In the majority of instances the trial quotient proves to be the true quotient. The need for repeating more than once the attempt to obtain the true quotient integer is relatively infrequent. "Underestimation," i.e., selection of a too small quotient integer, is not possible, due to the positive stop arrangements provided.

The preferred method of carrying out a cycle of operations in a division process in this machine is as follows: The value of the dividend digits in the two highest inboard orders of dials 8 of register 3, FIG. 2, the 20th and 19th dials, is sensed. In the initial cycle, the value in the 20th dial is "0," and in the 19th dial the value is that of the highest order integer of the dividend. The divisor selected plate element is set up in accordance with the sensed dividend value, so that the pertinent quotient value representation is at a sensing position. Then the set-up quotient representation is sensed and concurrently the multiplier controls in the computing mechanism are adjusted automatically for that trial quotient value. Next, a cycle of operations of the multiplying mechanism is instituted automatically, whereby the product of the divisor factor (the multiplicand) times the trial quotient digit (the multiplier) is subtracted from the dividend in register 3, and the trial quotient is registered in the first inboard order dial 7 of register 2, FIG. 1, the 10th or leftmost dial in the initial phase of the division process, at which time that dial is standing in alignment with the numeral "0" on the decimal marker channel 22.

When subtraction of the product does not result in an overdraft, as would be indicated on register 3, a cycle of operations is instituted automatically for shifting the carriage leftward one step. In the final phase of the shift cycle, operation of the division power unit is initiated again, this time automatically, except, however, when the carriage has been shifted to its leftmost position, or to a preselected ordinal position, or whenever the dividend has been eliminated, showing that a solution has been reached. In the event an overdraft occurs, the overdrafting amount and the too large quotient digit entries are withdrawn from the respective registers 3 and 2. At the same time, the dividing mechanism automatically reduces the value of the too large quotient digit by "1" and adjusts the multiplier controls accordingly. The multiplying mechanism is then automatically caused to obtain the product of the divisor factor times the reduced trial quotient value and to reduce the dividend by that product. If the value of a set up trial quotient or of a reduced trial quotient is "0," a shift cycle of operations for shifting the carriage one step leftward is instituted automatically, instead of initiating operation of the multiplying power unit.

Means are also provided for selectively indicating a reference point such as a decimal between adjacent orders of registers 2 and 3 and of the banks of keys 4.

The main frame of the machine embodying the invention includes base plate 23 (FIG. 3) to which rear and front plates 24 and 25 are fastened respectively, and plates 26 to 30 inclusive, which extend parallelly between the front and rear plates and are secured thereto and to base 23. The rightmost plate 31 is a short plate secured to the rear and base plates, and the upper forward end of plate 31 is secured to plate 30 by means of rod 32. A cross member 33 (FIG. 5) is secured to the upper faces of plates 26 to 30 inclusive, for making the frame structure more rigid.

Companion plates 34 to 39 inclusive, FIG. 3, are secured to each other in parallel planes as by shaft sections (not illustrated), the ends of which are formed for screwing one section to the other and for clamping the respective plate therebetween. The unit thus formed is fastened removably to plates 28 and 30 as by bolts which are not shown. This unit supports mechanisms actuated by various keys. Another frame unit, which supports the keys and the locking mechanisms therefor, is formed of the following plates: top 40, FIG. 6, bottom 41, front 42, rear 43, and side plates 44 and 45, which are similar and of which only left plate 44 is shown. This keyboard unit may be removably secured to companion plates 34 and 39 (FIG. 3) and to plate 26 in any well known manner.

In this exemplary embodiment, the carriage is formed of 25 vertical frame plates 46, as seen best in FIG. 3, which are secured at spaced locations to transverse frame members 47 and 48 and to feed bar 49. Further rigidity is added to the carriage frame by rods 50, 51 and 52 which are secured to several of the plates 46, including the end plates. Generally, the vertical plates 46 form ordinal compartments for supporting the 21 dials 8 of the product register and the 10 dials 7 of the multiplier register. Rod 51 has secured thereto a compressible cylinder 53 which actuates the tabulating mechanism at a preselected ordinal position and at each end position. Rods 51 and 52 are also utilized as rails by which the carriage is shiftably supported on four anti-frictional means 54 of which one pair is supported on frame member 27 and the other pair on frame member 30. Each means 54 (FIG. 6) includes a roller 55 rotatably mounted on a bracket 56 which is secured to the respective frame member. The rails ride on the rollers, and the brackets are formed to embrace the respective rails so as to prevent random removal of the carriage. In the illustration, frame member 27 and rail 51 are shown.

In addition to the product and multiplier register mechanisms, each including a dial and several gears in each order, the carriage also carries components of an add-subtract control for the product register, components of clearing and main carry mechanisms, and the outboard carry mechanism for the product register.

In this machine, as will be described, the need for carrying twice in an inboard order of the product register may occur during a partial product entry operation, such carries are effected by the main carry mechanism. Triggering means is also provided for causing the main carry mechanism to effect a carry at the same time in all inboard orders of register 3 standing consecutively at pre-carry, when the next lower order adjacent the lowest of such consecutive orders is rotated through tens carry position.

2. MULTIPLYING POWER UNIT

Multiplying power unit 57, FIG. 4, is formed of a sleeve 58 rotatably mounted on journaled shaft 59, a drive gear 60 and a speed-responsive governor 61 secured respectively on the left and right ends of the sleeve, and cams 62 to 69 inclusive, which are mounted on the sleeve 58 between the drive gear 60 and governor 61 with suitable annular spacers 70 therebetween. Components of governor 61, drive gear 60 and the interposed cams and spacers are secured together by rod means 71 for rotation as a unit.

Drive gear 60 may be entrained with or coupled to any suitable motor means for rotating power unit 57. In one preferred form, as described in the afore mentioned parent application, motor means represented schematically by 72 in FIG. 4 hereof is of the type which exerts rotative forces at all times on shaft 59 through gear means 73 secured thereto. The carriage and division power units, represented schematically by 74 and 75 respectively in FIG. 4 and are described in further detail in said parent application, are also mounted rotatably on shaft 59. For driving the several power units, two differential means, represented schematically by 76 and 77, are also provided. Differential 76, between division power unit 75 and the carriage power unit 74, is secured to shaft 59 for rotation therewith by a diametral pin or other means and is meshed with a suitable drive gear of the division power unit, and is sleeve and gear connected with differential means 77 for driving the same and/or the division unit 75. Differential means 77, between the carriage and multiplying power units, is meshed with a suitable drive gear of the carriage power unit 74 and with drive gear 60 of the multiplying power unit 57 for driving one and/or the other.

A stop-start means, responsive to manual and automatic control means, is provided for each power unit for initiating and stopping operation of its respective unit. The main operating mechanism is of the type that when all the power units are arrested, motor means 72 and shaft 59 are thereby also arrested, and that upon liberation of any one of the power units, the shaft and motor means are thereupon free to operate for turning the liberated unit. While one power unit is operating, another power unit may also be operated, as when the machine is cycled for division. At such times, during the latter phase of the operation of one power unit, operation of another power unit is started automatically for the ensuing appropriate steps of operation, until a solution is reached.

Through its gear 60, unit 57 is turned clockwise as when viewing its can 64 in FIG. 8. In a 360° revolution, the cams of the power unit actuate the computing mechanism for obtaining the product of a single digit multiplier times a multiplicand of one or more digits. Cam 64, cooperating with detent 78 of the stop-start mechanism holds the power unit in its stop-start position.

Detent 78 is pivotally mounted on the depending arm of bellcrank 79 which is fulcrumed at 80 on bracket 81 fixed to the main frame. The clockwise turning force of cam 64 presses detent 78 and bellcrank 79 rearwardly to where rear extension 82 of the bellcrank is stopped by buffer element 83 suitably secured on fixed bracket 81. A lever 84 is pivoted on the bracket 81 so as to extend rearwardly, generally parallelly with extension 82. On its free end, lever 84 carries a roller 85 which overlies extension 82. Coil spring 86 is seated on lever 84 and is fastened to lateral lug 87 on bracket 81 by an adjustable screw and lock-nut means 88. The upper profile 89 of extension 82 presented to roller 85 is such that spring 86 rocks bellcrank 79 clockwise against lateral lug 90 on bracket 81 when detent 78 is disengaged from cam 64. Thus, at such times, detent 78 is carried forwardly sufficiently so as to be resettable into the path of clockwise turning of cam 64, at a position in advance of the illustrated stop-start position of the cam. Then on re-engagement of cam 64 and detent 78, bellcrank 79 is rocked rearwardly, whereupon the upper profile 89 of its extension causes the lever 84 to move counterclockwise, recompressing spring 86. Hence, the power unit is retarded considerably by the increasing resistance of spring 86, before extension 82 contacts buffer 83.

Spring 91, as seen in FIG. 8, is fastened to detent 78 and the forwardly extending arm of bellcrank 79, so that it tends to rock the detent clockwise. The detent contact surface of cam 64 and the cam contact surface of detent 78 are so formed that in response to the influence of springs 86 and 91 and the clockwise directed turning force of the cam, the detent is moved upwardly out of the path of the cam when the detent is free to so move. Normally, detent 78 is held in engagement with cam 64, as illustrated, by member 92 which is pivoted on

fixed bracket 81. Member 92 extends forwardly in the machine and has a lateral lug 93 overlying detent 78 and further forward it has another lateral lug 94 which latched by a rockable latch 95 so as to prevent clockwise turning of the member by detent 78. Disengagement of latch 95 from member 92 allows the detent 78 to disengage from cam 64 as set forth above. The forward portion of member 92 is received in guide slot 33a (FIG. 5) on frame member 33, which limits the upward or clockwise swing of member 92, FIG. 8. Lateral lug 96 on the generally horizontal arm of bellcrank 97 overlies member 92 in operated position and is provided for returning the member. Bellcrank 97 is pivoted coaxially with member 92 on bracket 81, and the depending arm of bellcrank 97 carries roller 98 which at all times rides the periphery of cam 66 under the influence of spring 99, fastened to bellcrank 97 and member 92. The profile of cam 66 is such that during the initial phase of its clockwise revolution, it rocks bellcrank 97 counter-clockwise sufficiently to effect re-engagement of member 92 with latch 95 and, at the same time, cause member 92 to return detent 78 into the path of cam 64 for stopping the power unit at the completion of one revolution, as described. In the latter phase of its revolution, cam 66 allows bellcrank 97 to return to its illustrated normal position.

Latch 95 is interposed bellcrank 100 and lever 101, all pivotally mounted on shaft 102 which is fixed on the machine frame. The depending arm of bellcrank 100 is formed with lateral lug 103 which normally is against the depending arm of latch 95 so that clockwise movement of bellcrank 100 rocks the latch clockwise for disengaging it from member 92. Torsion spring 104, fastened to bellcrank 100 and latch 95, influences the latch and bellcrank toward each other to normally hold the depending arm of latch 95 against lug 103. A lever 105, pivotally mounted on shaft 106 which is secured on the frame, has hook 107 pivoted on its depending arm. Hook 107 extends rearwardly between the depending arms of latch 95 and of bellcrank 100, and is latched onto lug 103 of bellcrank 100 and overlies lug 93 of member 92. Spring 108 is fastened to the upper arm of bellcrank 100 and to hook 107 for holding bellcrank 100 against stop member 109 secured to the machine frame, and for influencing hook 107 clockwise and lever 105 counter-clockwise to their normal positions, as illustrated. As disclosed in the above identified parent application, a positive stop arrangement is provided for the normal position of lever 105, and the lever is rocked clockwise in response to operation of any multiplier (value 1 to 9), add and subtract key. At such times, hook 107 is moved forwardly for engaging its hook formation 107a with 103 and for therethrough rocking bellcrank 100 clockwise to trigger the stop-start means, as described above.

Lug 103 also stands in the path of clockwise movement of lever 101 which is connected by link 110 to lever 111 secured to journaled shaft 112. As described in the parent application, transverse shaft 112 is turned counter-clockwise each time a trial quotient other than "0" is obtained. The arrangement is such that lever 101 is then swung clockwise thereby to effect triggering of the stop-start means.

3. MULTIPLICATION ELEMENTS

For each bank of keys 4, FIG. 1, a group of 10 multiplication elements 120 to 129, inclusive, FIG. 9, is provided. All the elements or plate devices are pivotally mounted at their forward ends on transverse shaft 130, journaled on the machine frame for being rotatable in opposite directions. The elements 120 to 129 are releasably clamped near their rearward ends in rest position by a pair of transverse rods 131 and 132, except during a multiplying cycle of operations. Rods 131 and 132, as described in the parent application, are movable toward each other by toggle means against fixed stop 133 (FIG. 7) on the machine frame, common to the rods at the end portions thereof. For clarity the multiplication elements are omitted from FIG. 7. Each element 120-129 (FIG. 9) is formed with a slot 134 generally concentric with its axis,

through which the rods 131 and 132 extend, and with a web 135 intersecting the slot for receiving directed force from the rods for at times holding all the elements at rest position. Upon release of toggle pressure early in a multiplying cycle of operations, the rods 131 and 132 are free to swing angularly about the axis of shaft 130.

Each multiplication element 120 to 129 represent a multiplicand integer 0 to 9, as indicated by the last digit of the reference numeral therefor, and is formed with two sets of stepped stop surfaces or stations disposed angularly with respect to shaft 130. The stations of elements 120 to 124 may be more clearly seen in FIG. 10, and of elements 125 to 129 in FIG. 11. Stations 140 to 148 and 150 to 159 of an element are arranged differentially substantially radially with respect to shaft 130 to represent respectively the tens and units integers, as indicated by the last digit of the reference numeral therefor, of the product of that element value times multipliers 1 to 9.

As disclosed in the parent application, depression of a key 4 (FIG. 1) for value 1 to 9 effects selection of the related element 121 to 129 for set-up operations. If, however, a key 4 in a bank is not depressed, the 0 value element 120 associated with that bank is automatically selected for the set-up operations, the selecting mechanism normally standing in alignment with the zero value element. During a multiplying cycle of operations, the selected multiplication element of each group is moved angularly a predetermined angular extent from rest position in accordance with the multiplier digit value, and suitable means are provided for holding the non-selected elements in each group in their rest positions, as disclosed in the parent application.

Referring to FIG. 9, a set or pair of generally U-shaped, independently rockable feeler or sensing members 160 and 161 depend to each group of elements 120 to 129 from transverse shaft 162 which is fixed on the machine frame. The ten groups of multiplication elements and the set of feeler members 160 and 161 for each group are alike, hence the description of one group of elements and its set of feeler members will also describe the others. Member 160 is inset within member 161, and the horizontal sensing portion of each is in transverse relation to the elements. Each feeler member, as will be described, is rocked counter-clockwise until it is stopped by contact with a station on the displaced multiplication element. The arrangement is such that feeler member 160 is stopped by a tens station 140-148 and feeler member 161 is stopped by a units station 150-159 of only the selected and hence displaced element. Two slot means 163, one for each feeler member, are so formed on each element that, in rest position of an element, the feeler members may move freely therein until they contact the selected and hence displaced element.

As described in the parent application, the selected multiplication element 120 to 129 is elevated from rest position as many steps for multipliers 1 to 4 as the value of the multiplier, or is depressed from rest position 1, 2, 3, 4 and 5 steps respectively for multipliers "5" to "9." The tens and units stations on each element are arranged accordingly, so that at each displaced position of an element its tens and units stations standing in the path of movement of the feeler members represent the product of the respective multiplier value times the multiplicand value of the element. The relationship between the stations and the related feeler members is such that each station stops its related feeler member upon a counter-clockwise swing of as many steps as the value of that station. If, for example, the multiplicand digit of an order is "9" and the multiplier digit is "8," the related element 129 (FIG. 11) is selected and then depressed four steps, whereupon its tens station 147 and units station 152 stand to stop respectively feeler 160 (FIG. 9) upon a swing thereof of 7 steps, and feeler 161 upon a swing thereof of 2 steps. Such steps of extents of movements of the feelers, as will be described, effect actuation of the product register to indicate the product, which in the above example is "72."

4. SUPPORT UNIT FOR REGISTER ACTUATING MECHANISMS

Eleven orders of product register actuating mechanisms are provided, i.e., entry and carry mechanisms, one for each group of multiplication elements and an overflow order, and a multiplier dial actuating mechanisms is also provided. These mechanisms are normally disengaged from the associated in-board orders of the respective product and multiplier registers. A movable support unit is provided for carrying the product entry and carry mechanisms and the multiplier entry mechanism into and out of engagement with the respective in-board register orders. The support unit is formed of left bar 164 (FIG. 12) and companion right bar 165 (FIG. 13) which are secured at their forward ends to journaled shaft 136, and transverse shaft 166 is secured to and interconnects both bars rearward from shaft 136. The unit 164, 165, 166 thus formed is elevatable, i.e., as viewed in FIG. 13, it is rotatable counter-clockwise about the axis of shaft 136. Stud 167 on bar 165 carries a roller 168 which, in rest position of the support unit, as illustrated, overlies power unit cam 62, the periphery of which is such that in the initial phase of its clockwise revolution it elevates the support unit 164, 165, 166 sufficiently to effect engagement of the entry and carry mechanisms with the inboard dials on the carriage. The support unit is locked automatically in elevated position normally, by suitable means, until the entry and carry operations are completed. Then the support unit is returned to rest position, at which time the supporting portion of the periphery of cam 62 is again in position so as to be engaged again by roller 168.

In FIG. 12, bar 164 is shown in normal position of the support unit, that is, its lower position, with roller 169 mounted on shaft 166 in contact with stop surface 170 on detent 171 for blocking counter-clockwise turning of the detent which is pivotally mounted on fixed stud 172 on the machine frame. Torsion spring 173 is fastened to detent 171 and fixed stud 174 on the machine frame for turning detent 171 counter-clockwise when the support unit is elevated sufficiently to move roller 169 out of the path of stop surface 170. Finger 175 (FIG. 14) of detent is provided for limiting the counter-clockwise movement of the detent by contacting roller 169, as illustrated. At this position of the detent, its surface 176 underlies the roller to hold the support unit 164, 165, 166 in elevated position as shown.

Detent 171 is rocked clockwise, as will be described later, for returning the support unit to normal position, thereby effecting disengagement of the entry and carry mechanisms for the carriage borne mechanisms after entry and carry operations are completed. The upper extremity of detent 171 is generally C-shaped, the internal contour 177 thereof being such that during the initial phase of the clockwise stroke of the detent, it cooperates with roller 169 to positively return the support unit to normal position again as shown in FIG. 12. During the latter phase of the clockwise stroke of detent 171, i.e., after the entry and carry mechanisms are disengaged, the detent normally effects initiation of a shift cycle of operations for a one-step movement of the carriage, as described in the parent application.

5. PRODUCT REGISTER ACTUATING AND CARRY MECHANISMS

The eleven orders of the product register entry and carry mechanisms are substantially the same, hence the description of one order will also describe the other orders. Referring to FIG. 9, companion members 178 and 179, each adjacent to a group of multiplication elements on opposite sides of the group of elements at a forward portion thereof, are rockably mounted on transverse shaft 180 which is journaled on the machine frame. Members 178 and 179 (FIG. 15) are twin armed at their generally upright free ends, and are secured together therat, as by rod 181 at one of the arms and by tubular rod or sleeve 182 at the other of the arms, to form rockable

unit 183. Members 178 and 179 may be secured together still further as at their pivotal ends by a sleeve 184. Crank arms 185 and 186 are secured, opposingly each to a different end of rod 187 rockable in sleeve 182. The crank arms extend radially in opposite directions, and depending crank arm 185 is connected by link 188 to units feeler member 161 of the respective order, and generally upright crank arm 186 is connected by offset link 189 to the tens feeler member 160 of the adjacent lower order. The rearward end of link 189 in the first order and of link 188 in the eleventh, i.e., the last, order are secured to suitable stationary frame members, there being respectively no lower order tens sensing member and no units sensing member in the overflow order. Unit 183, as will be described, is turned clockwise, i.e., moved rearwardly, to rock the connected sensing members 160 and 161 rearwardly against the respective set up multiplication elements. The arrangement is such that the unit 183 will move rearwardly until both sensing members are stopped by the set up multiplication elements, the extent of movement of 183 being the total steps of movement of both sensing members. Hence, unit 183 may move a maximum of 17 steps, as when "19" is multiplied by "9."

$$\begin{array}{r}
 1 \ 9 \\
 \times 9 \\
 \hline
 8 \ 1 \\
 9 \\
 \hline
 17 \ 1
 \end{array}$$

30 The unit 183 of the order in which the 1 of "19" is being computed moves a total of 17 steps or extents, 8 steps with sensing member 160, as limited by the tens product station 148 (FIG. 11) of element 129, and 9 steps with sensing member 161, FIG. 15, as limited by the units product station 159 (FIG. 10) of element 121.

35 Referring to FIG. 15 again, rod 181 is passed through elongated slot 190 on rack member 191 for slidably supporting the forward portion of the rack member and for moving the rack member rearwardly, the slot being of utility in carry operations as will be described. Rearward movement of rack member 191, as will be described, turns the product dial entrained therewith to register the value of the total of the sensed unit partial product of that order and of the sensed tens partial product of the adjacent lower order. Thus, in the above example, in the order in which unit 183 moves 17 steps, rack member 191 also moves 17 steps, turning the entrained dial to register "7" and to effect a carry of "1" in the adjacent higher order dial.

40 The forward end of rack member 191 (FIG. 17) has pivoted thereon bellcrank 192, the generally upright arm thereof being connected by link 193 to rod 181 and the rearwardly extending arm thereof being formed with lateral lug 194 so as to underlie the end of depending arm of bellcrank 195, pivotally mounted on rack member 191. The arrangement is such that clockwise and counter-clockwise turning of bellcrank 192 and rearward movement of rack member 191 are normally blocked in a position where rod 181 is in contact with the rearward end of slot 190. Spring 196 is fastened to shaft 162 and bellcrank 192 so as to exert clockwise turning force on the bellcrank and therethrough exert rearward pull on rack member 191 and the unit 183. The other arm of bellcrank 195 extends rearwardly and is formed with lateral lug 197 so as to overlie member 198 which, at its forward end, is formed with slot 199 for slidable mounting on rod 181. Lug 197 is also in contact with stepped stop 200 on member 198 so as to normally block member 198 from moving forwardly of rack member 191 and, conversely, to prevent the rack member from moving rearwardly of member 198, under the influence of spring 201 fastened to the member and the rack member. As illustrated, in this position of member 198, the rearward end of its slot 199 is in contact with rod 181. Spring 201 also influences member 198 counter-clockwise. Return spring 202, fastened to bellcrank 195 and rack member 191, urges the bellcrank 195 counter-clockwise to engage member 198 and

bellcrank 192, as set forth above. Through bellcrank 195, spring 202 also urges member 198 counter-clockwise to rest position whereat integral lateral lug 203 on the free end of 198 contacts rack member 191. Another lug 204 is provided on the free end of member 198 so as to situate below rack member 191 to contact rack member 191 for blocking member 198 upon movement thereof a predetermined angular extent clockwise. Parts 192, 193, 195 and 198 and slots 190 and 199 are primarily for carry operations. These parts and slots are not provided in the first order entry mechanism, there being no carry to that order. In the first order, the forward end of spring 196 (FIG. 9) is fastened to rack member 191 which is mounted only for turning on rod 181. Each rack member 191 is provided with lug 205 which stands in the path of forward (counter-clockwise) movement of bail 206 common to all the rack members. Bail 206 (FIG. 15) and lever 207 are secured to journaled shaft 180 for movement therewith. Return spring 208 (shown in part only), fastened to lever 207 and the machine frame, is of sufficient tension to turn bail 206 counter-clockwise for moving rack members 191 forwardly to rest position and for thus reloading springs 196, FIG. 17. The forward or return movement of rack members 191 (FIG. 15) is limited by the related feeler members 160 and 161 contacting fixed transverse stop shaft 209 which is supported on the machine frame.

Lever 207 is connected by link 210 to the depending arm of follower 211, FIG. 16, which is pivotally mounted on shaft 212. Another arm of follower 211 carries roller 213 which rides the periphery of power unit cam 65 under the influence of spring 208, FIG. 15. The arrangement is such that, subsequent to the set up of the selected multiplication elements, cam 65 (FIG. 16) rocks follower 211 counter-clockwise, moving link 210 rearwardly to rock bail 206 (FIG. 15) clockwise sufficiently to allow rack members 191 to move rearwardly to effect entry operations in the entrained dials, as limited by the sensed product stations on the selected, set-up elements, and by the carry components.

A rack member 191 will move 17 steps when, for example, "19" is multiplied by "9," as explained hereinbefore. If the dial entrained with a rack member moving the 17 steps stands at zero at the start of the operation, the dial will rotate through "9" to "0" once (in additive operations) in order to indicate the "7" of the 17. If, however, the dial stands at "9" at the start of the operation, the dial will rotate through "9" to "0" twice during a single 17 increments entry stroke of rack member 191, to indicate the "6" of "26," the sum of nine and 17. From the foregoing it follows then, that, e.g., in additive operations, the combined total of the digit initially in a dial and the partial product added into that dial is a number "10" to "19" inclusive, the dial rotates through tens carry once, and when the combined total is "20" to "26" (the highest total obtainable in this embodiment) the dial rotates through tens carry twice. Each time an inboard dial turns through tens carry, either in additive or subtractive operations, it actuates triggering means (to be described further hereinafter) provided for effecting oscillation of member 198 (FIG. 17) in the adjacent higher order to cause a carry therein. Such a member 198 is elevated momentarily through its lug 203, to rock bellcrank 195 clockwise sufficiently to disengage its depending arm from lug 194 of bellcrank 192 and place stop 214 on the arm into the path of lug 194. Hence, bellcrank 192 is free to turn clockwise about its pivotal connection with link 193 and moves rack member 191 rearwardly under the influence of spring 196, until lug 194 contacts stop 214. Thus rack member 191 slides rearwardly on rod 181 one step, thereby rotating the entrained dial to indicate "1" carry, as limited by the blocked bellcrank 192. Through bellcrank 195, the rack member may also move member 198 rearwardly, the slot 199 thereon limiting the movement of member 198. Bellcrank 195 (FIG. 18) is held in its first operated position against return spring 202 by bellcrank 192. Hence, on the return downward stroke of member 198, under the influence of spring 201, its stop 200 disengages from bellcrank lug 197, and spring 201

then pulls the member forwardly to rest position as limited by rod 181 and slot 199. Stop 214 blocks clockwise movement of bellcrank 192, whereby bellcrank 192 holds rack member 191 in its first carry operated position. The arrangement is such that when member 198 is in rest position and bellcrank 195 is in its first operated position, bellcrank lug 197 overlies the uppermost edge of member 198. Thus elevation again of member 198 in response to the dial in the adjacent lower order passing through tens carry a second time in one entry cycle of operations, will rock bellcrank 195 further clockwise (FIG. 19) to disengage its stop 214 from lug 194 of bellcrank 192 which, under the influence of spring 196, then turns further clockwise about its pivotal connection with link 193. This second clockwise turning movement of bellcrank 192 causes rack member 191 to move rearwardly one step, as limited by rod 181 and slot 190, to rotate the entrained dial to indicate another carry of "1." The need for a third carry in a single entry cycle of operations does not occur. The return forward movement of rack member 191 (FIG. 17) by bail 206 causes bellcrank 192 to turn counter-clockwise to rest position, whereupon bellcrank 195 is returned by spring 202.

Toward its rearward end each rack member 191 (FIG. 9) is formed with elongated slot 215 and is bifurcated, with racks 216 and 217 formed internally on the furcations. Movable transverse rod 218 is passed through slots 215 for slidably supporting the rack members in additive and subtractive entry position. The rack member is illustrated in additive position, in which rack 216 is meshed with gear 219 rotatable on the afore described support unit shaft 166. Gear 219 is secured to gear 220 of larger diameter, which meshes with the carriage borne gear 221 (FIG. 14) in engaging relation therewith, when the support unit 164, 165, 166 is elevated, as previously described. When the support unit is in rest position, gears 220 and 221 are disengaged as illustrated in FIG. 12. In each order of the product register, a gear 221 rotatable on shaft 222 fixed on the carriage frame, is meshed with gear 223 to which dial 8 is secured, the dial gear 223 being rotatable on shaft 224 fixed on the carriage frame. The arrangement is such that 10 steps of movement of rack member 191 (FIG. 9) effects a 90° revolution of gear 221 (FIG. 14) and therethrough a 360° revolution of dial 8, the ratio between gears 221 and 223 being 4 to 1.

For subtractive entry of products, rod 218 is moved downwardly, as will be described, sufficiently to engage rack 217 (FIG. 9) with gear 219 and to disengage rack 216 therefrom, with one rack partially engaging gear 219 before the other is fully disengaged therefrom. The upward or additive and the downward or subtractive positions of rod 218 are defined by slots 225, FIG. 12, one on each support unit member 164 and 165, FIG. 13, through which the rod extends. At its right end, rod 218 (shown in a add position) is secured to the generally horizontal arm of bellcrank 226 which is pivotally mounted on support unit member 165. The depending arm of bellcrank 226 is connected by link 227 to the upright arm of lever 228 which is secured to transverse shaft 229 journaled on the machine frame. Correspondingly, the left end of rod 218 (FIG. 14) is secured to the generally horizontal arm of bellcrank 230 pivoted on support unit member 164, and link 231 connects the depending arm of bellcrank 230 to upright lever 232 secured to shaft 229. The arrangement is such that counter-clockwise turning of shaft 229, as when viewed in FIG. 13, effects downward movement of transverse rod 218 to condition the entry mechanism for subtractive operations. Normally, rod 218 is held in its uppermost position for additive operations through the clockwise influence of torsion spring 233 on lever 228, the spring being fastened thereto and to any suitable stationary frame member.

The following means is provided for turning shaft 229 to effect subtractive entries: As seen in FIG. 13, the depending arm of lever 228 has swiveled thereon hook 234 which, at a rearward portion thereof, is held in rest or normal position by link 235 connected thereto and to the free forward end of lever 236 which is pivotally mounted on optionally rockable key

lever 237 pivoted on stud 238 on the machine frame. The forward end of lever 236 is formed with lateral lug 239 which normally underlies the shank of subtract key 17, against which it is held by spring 240 fastened to lever 236 and stud 238. In this position of lever 236, depression of key 17 rocks lever 236 counter-clockwise, lowering hook 234 into the path of clockwise movement of lever 241, rotatable on shaft 209, so that upon clockwise rotation of lever 241, its lateral lug 242 engages hook 234 and moves the hook rearwardly to turn shaft 229 counter-clockwise, thereby moving rod 218 to its subtractive position, as set forth. By moving key lever 237 counter-clockwise, i.e., forwardly, to a predetermined position, as described in the parent application, lever 236 is shifted forwardly so that its lug 239 underlies add key 16 instead of subtract key 17, alternating the character of the keys for convenience, at the discretion of the operator.

For "negative" multiplication, automatically actuated means is provided, as described in the parent application, for rocking lever 236 counter-clockwise, when the lever is in its forward position. For subtractive entries in division, lever 236 is moved downwardly by stud 243 on the free end of lever 244 which is rockable clockwise automatically on fixed shaft 245 by means responsive to divide key operation, as described in the parent application.

Lever 241 is held yieldably against lug 246 on lever 247 by torsion spring 248 fastened to the levers. Lever 247 and multi-armed lever 249 (FIG. 20) are secured to the ends of sleeve 250 fixed to shaft 209 which is journaled on the machine frame. A pair of generally diametrically opposed arms of lever 249 are connected by links 251 and 252 to follower 253 oppositely at generally diametrically opposed locations thereon. Follower 253, pivotally mounted on shaft 212, carries roller 254 which overlies the periphery of power unit cam 63, and is held against the cam under the influence of torsion spring 255, fastened to the follower and the machine frame. Early in its clockwise revolution, cam 63 moves follower 253 counter-clockwise for rotating lever 249 clockwise, as through the rearward pull force on link 252, and a dwell portion on cam 63 holds the moved parts in operated position until the final phase of its revolution. When all entry and carry operations are completed, roller 256 mounted on cam 63 engages arm 257 of follower 253, then standing in its path of movement and positively swings follower 253 clockwise, back to rest position. This clockwise movement of the follower pulls link 251 for swinging lever 249 positively counter-clockwise, back to normal position. Various mechanisms connected to lever 249 and shaft 209 are thus actuated, as disclosed in the parent application, including the moving of rod 218 (FIG. 13) from its additive position to subtractive position and back again to additive position in each multiplying cycle of operations, as set forth, when the machine is set for subtractive entries of products.

6. MEANS FOR EFFECTING CARRY

The following describes the apparatus and operation for a crawl-like or consecutive carry.

A comblike member 258, FIG. 12, with a depending tine for each dial gear 223 and formed of suitable flexible material, is secured to bar 47 of the carriage frame. The end of each tine of member 258 is crimped for engaging the gear between the teeth thereof for yieldably holding the related dial 8 in any of its number displaying positions to which it may be turned, and for holding related gear 221 in proper meshing relation for engagement therewith of associated gear 220, as explained. The means for effecting carry triggering provided in each dial order, except the highest order, is substantially the same in each order, hence the description of one order will also describe the other orders.

A stiffening member 259 (FIG. 21) is secured internally to cylindrically formed dial 8 of carrying lateral stud 260 for movement with the dial about the axis of shaft 224. A lever member 261 is pivotally mounted on carriage frame shaft 50,

and extends forwardly and under shaft 222, against which it is held yieldably under the counter-clockwise influence of torsion spring 262, fastened to lever 261 and to the carriage frame. The free end portion of lever 261 is adjacent to the open end of dial 8 and is formed with lateral lug 263 extending rightwardly and with leftwardly extending, inverted V-shaped extension 264 which stands in the path of movement of stud 260. The relationship between the stud and the V-shaped extension is such that in additive pre-carry standing of the dial, stud 260 is in contact with one face of the V-extension, and that in subtractive precarry standing of dial 8, stud 260 is in contact with the other extension face, as shown. Thus, in each instance, upon further rotation, clockwise in additive and counter-clockwise in subtractive operations, of dial 8, stud 260 acts on the contacting face to move lever member 261 downwardly momentarily, which is then returned to its illustrated position by spring 262.

In each order of the entry and carry mechanism, except the overflow order, a rearwardly extending lever 265, formed with lateral lug 266 on its free end, is secured to the right end of sleeve 267 which is turnable on shaft 268 carried by the afore described entry and carry mechanisms support unit 164, 165, 166. Sleeve 267 has secured thereto a depending lever 269 which carries lateral lug 270 on its free end extending leftward toward the adjacent higher order section. The arrangement is such that when the entry mechanisms are elevated to mesh, each with its associated dial gearing, as described, bellcrank means 271, formed of parts 265, 267 and 269, is carried upwardly into contact engagement of its lug 266 with lug 263 of lever member 261. Consequently, when the lever member is moved downwardly, bellcrank means 271 is rocked counter-clockwise, against the tension of return spring 272 fastened at one end to lever 269, which spring will be described more fully later. Bellcrank member 273, FIG. 22, pivotally mounted on shaft 218, carries lug 274 on its depending arm, which lug extends rightward and at all times is in contact with lug 270 of bellcrank means 271 so that the counter-clockwise rocking thereof by the associated dial, as described, moves bellcrank 273 counter-clockwise. The other arm of bellcrank member 273 extends forwardly and is pivotally connected at its free end to L-shaped member 275 at the junction of its two legs, one of which extends forwardly and contactingly underlies lug 203 of member 198. The other leg of member 275 depends to lever 276 and is pivotally connected thereto for rectilinear movement, the lever being substantially parallel to the forward arm of bellcrank 273 and rockable on shaft 277 secured on the machine frame. Thus, upon counter-clockwise movement of bellcrank means 271, member 275 is moved upwardly sufficiently to elevate member 198 for effecting a carry of "1," as described. It is thus seen that the afore described triggering and carry operations, from one order to the adjacent higher order would progress in a consecutive or crawl-like manner, during the product registration operation.

7. MEANS FOR EFFECTING SIMULTANEOUS CARRY

If, for example, several consecutive orders of dials 8 (FIG.

60) stand at pre-carry, or progress to a pre-carry position during product entry, and a carry of one from the lowest of such orders occurs, the afore described triggering and carry operations from one order to the adjacent higher order would progress in consecutive or crawl-like manner. While the disclosed mechanism would perform such crawl-like operations very rapidly, the process is hastened by means provided to simultaneously perform carry triggering in all consecutive orders in which triggering is to occur and has not yet been accomplished.

Referring to FIGS. 13 and 23, a bail means, carried by the support unit 164, 165, 166, is formed by forwardly extending lever 278 and bellcrank 279 being secured respectively to the right and left ends of transverse shaft 280 journaled on support unit members 164 and 165, and with bail rod 281 being passed through a slot 282 substantially concentric with the

axis of shaft 280 on each of the members 164 and 165, and being secured on its right and left ends respectively to the free end of lever 278 and to the forwardly extending arm of bellcrank 279, FIG. 23. The depending arm of bellcrank 279 is formed with slot 283 in which stud 284 on the rearward end of bar 285 is slidably received, and spring 286 is fastened to the bar and bellcrank for yieldably holding stub 284 against the rearward end of slot 283 for at times rocking bellcrank 279 counter-clockwise in response to forward rectilinear movement of bar 285. The forward end of bar 285 is pivotally connected to the free end of the upright arm of lever 287 pivoted on stud 288 on the machine frame, and the depending arm of lever 287 is connected by link 289 to depending lever 290 secured to the left end of journaled shaft 103. Follower 291, secured to a rightward portion of shaft 103, carries on its free end roller 292 which rides the periphery of cam 62. Under the counter-clockwise influence of return spring 293, fastened to lever 290 and the machine frame, bail rod 281 is held against the support unit members at the lower end of the slots 282 and follower roller 292 is held against the cam. The arrangement is such that at about the time the product entry operations are completed, cam 62 rocks follower 291 clockwise for effecting forward movement of bar 285, whereby bellcrank 279 turns counter-clockwise until rod 281 is stopped by the support unit members at the upper end of the slots 282 thereon. Thereafter, bar 285 moves forwardly, against the rearward influence of return spring 286, with stud 284 sliding forwardly in bellcrank slot 283.

Two longitudinally spaced lateral lugs 293 and 294 are carried on the forward portion of bar 285. The free end of depending lever 295, pivoted on transverse shaft 268 journaled on the support unit, stands in the path of lug 293 so that, at about the time the upward movement of bail rod 281 is stopped, lug 293 contacts lever 295 for turning the same counter-clockwise. Lever 295 is formed with a lateral lug 296 which extends through a suitable opening formed on member 164 and underlies rearwardly extending lever 297 secured to shaft 268. Spring 298 is fastened to lug 296 and lever 297 for yieldably holding the lever against the lug for turning movement of lever 297 and shaft 268 together with lever 295. A vertical link 299 is pivotally connected to the free end of lever 297 and to the forward arm of lever 300 which is pivoted on the end of support unit shaft 166. Return spring 301, of lesser tension than spring 298, is fastened to lever 300 and support unit member 164, and influences the lever counter-clockwise to normal position as limited by lug 296 contacting stop surface 302 formed by the opening on member 164. Left leg 303 of transverse bail member 304 is pivotally connected to the free end of the rearward arm of lever 300. Companions to parts 297, 299 and 300 are provided on right member 165 (FIG. 13) of the support unit for uniform support and movement of bail member 304, as follows: Lever 305, secured to journaled shaft 268, is connected by vertical link 306 to the forward arm of lever 307 which is pivoted on the right end of shaft 166 and has leg 308 of bail member 304 pivotally connected to the free end of its rear-arm. By these linkages and levers, counter-clockwise movement of lever 295 (FIG. 23) effects elevation of bail member 304. An upright projection 309 is formed on bail leg 303 for standing in the path of clockwise movement of lateral lug 310 on lever 311 pivoted at 312 on support unit member 164. Lever 311 is influenced counter-clockwise against stud 313 on the depending arm of bellcrank 279 by projection 309 through the counter-clockwise urging of torsion spring 314 between bail 304 and lever 300. Thus, through stud 313 counter-clockwise movement of bellcrank 279 rocks lever 311 and therethrough bail member 304 clockwise.

On forward movement of bar 285, first, bellcrank 279 is rocked counter-clockwise for elevating rod 281 and for turning bail 304 clockwise to operating position, for effecting preparatory operations for simultaneous carry; second, lever 295 is turned counter-clockwise for elevating bail member 304 for effecting triggering for simultaneous carry, all as will

be further described, and third, upon completion of simultaneous carry operations, lug 294 on bar 285 engages lug 315 on the depending arm of lever 316, pivoted on the machine frame, for rocking the lever counter-clockwise against the tension of its return spring 317, FIG. 12, fastened to the lever and frame 28, which spring normally holds the lever in rest position with its lug 315 against stop surface 318 provided therefor on the frame. The upper arm of lever 316 carries stud 319 which is normally latched by spring tensioned hook 320, as described in the parent application, Ser. No. 194,273, filed Nov. 6, 1950, for Partial Product Calculating Machine, now U.S. Pat. No. 2,969,177, issued Jan. 24, 1961. Hook 320 is pivotally mounted on member 321 which is rockable on shaft 322 secured on the machine frame. Depending lever 323, pivoted on shaft 322, is formed with lug 324, which overlies the generally forwardly extending arm of member 321, and is further formed on its depending free end with elongated slot 325 in which stud 326 on the forward end of link 327 is slidably received. The rearward end of link 327 is pivotally connected to the afore described detent 171, and, upon elevation of the support unit and the consequent counter-clockwise turning of detent 171 to hold the unit in elevated position, stud 326 moves from the forward to the rearward end of slot 325. Then, when lever 316 is turned counter-clockwise, through the parts including 320, 321, 324 and 327, detent 171 is turned clockwise sufficiently to effect return of the support unit and the consequent disengagement of the entry and carry mechanism from the inboard orders of the carriage borne digits, as described herein, and to effect initiation of carriage shift operations, as described further in the parent application.

A member 328 (FIG. 23) formed of suitable flexible material with ordinal fingers 329, one for each order (except the lowest and overflow orders) of the entry and carry mechanism, is secured to bail member 304. Fingers 329 project upwardly and their ends are bent over to form suitable supporting surfaces. In relation to each finger 329, a lever member 330 (FIG. 24) is pivoted on shaft 166 with its rearward arm resting on shaft 280 and with its forward arm having a slot for receiving stud 331 on the rearwardly extending arm of bellcrank 332, which is pivoted on shaft 268 in proximity to the afore described member 269 of bellcrank means 271. The depending arm of bellcrank 332 carries lateral lug 333 which stands in the path of counter-clockwise movement of member 269 and is in contact therewith under the influence of torsion spring 334 between bellcrank 332 and member 269. Spring 272, of lesser tension than spring 334, is fastened to lever member 330 and to member 269, for exerting counter-clockwise turning force on lever member 330, holding member 330 against shaft 280, and for exerting clockwise turning force on bellcrank means 271 for holding the same as limited through bellcrank 332 by the blocked lever member 330. It will be recalled that each time bail means 271 (FIGS. 21) is oscillated (first turning counter-clockwise, then clockwise) in response to turning of its related dial 8 through tens carry, member 198 (FIGS. 17 and 22) in the respective adjacent higher order is elevated and returned to rest position for effecting a carry in that higher order, as described. Hence, member 330 (FIGS. 24) of such a lower order is rocked clockwise and is normally returned immediately again to rest position.

The rearward end of lever member 330 is formed with latch means 335, which, in rest position of the member, stands in the path of clockwise turning of its related finger 329 when bail member 304 is so turned, as described, at the completion of entry operations. Thus, flexible fingers 329 are pressed against members 330, and if any member 330 is rocked clockwise before bail member 304 is moved upwardly, as previously described, the related finger 329 snaps in under latch means 335 for holding related parts 330, 332, 271, 273 (FIG. 22) and 275 in their operated positions. Hence, member 198 (FIG. 17) is held in elevated position and another (unwanted) triggering operation cannot be effected in that order until the respective member 198 is again lowered, as previ-

ously described. A member 330 (FIG. 24) being held in operated position by related finger 329 will be referred to as being in "latched position."

The rearward portion of each member 330 is formed with a lateral extension 336 which extends toward the adjacent higher order member 330 (FIG. 25) which has pivoted thereon a depending coupler 337 for at times engaging extension 336 of the adjacent lower order member 330. Coupler 337 is formed with a notch 338 (FIG. 24) and with face 339 on its free end, each for at times engaging the related extension 336. Coupler 337, tensioned counter-clockwise by spring 340 fastened thereto and to member 330, is also formed with lateral lug 341 which in rest position of the coupler, is in contact with member 330, and by which the coupler is rocked clockwise (as will be described) to couple with extension 336. The relationship between coupler 337 of one order and extension 336 of the adjacent lower order is such that when member 330 of the higher order is in normal position and member 330 of the adjacent lower order is in "latched position," its extension 336 is in alignment with notch 338 of the related higher order coupler 337. Then, when such a higher order coupler 337 is rocked clockwise in response to sensing of the pre-carry standing of the dial in that higher order, as will be described, the coupler couples with the lower order extension 336 so that elevation from "latched position" of the lower order member 330 also elevates the higher order member 330. If, for example, the dials in three consecutive orders stand at pre-carry, and carry is performed in the lowest or first of such orders, and the crawl process carry operations have not yet been performed in the second and third of such orders, member 330 of the first order is then in "latched position" and coupler 337 of the second order engages extension 336 of the first order by means of its notch 338, and coupler 337 of the third order swings clockwise to position its engaging face 339 in the path of upward movement of extension 336 of the second order so that elevation of the second order member 330 by the first order member also moves the third order member 330 upwardly. Accordingly, during the interim that bail member 304 is moved to its clockwise position and is elevated, through the crawl process carry more than one member 330 may latch on to member 328 carried by bail member 304, and in all consecutive adjacent higher orders, wherein the dials stand at pre-carry, the related members 330 are coupled to each other and the lowest order of such members is coupled to the adjacent lower order member 330, then in "latched position," for elevation by the "latched position" member upon upward movement of bail member 304. Elevation of any member 330 from its "latched position" rocks related bellcrank 332 counter-clockwise against the tension of spring 334, bellcrank means 271 (FIG. 22) and parts 273, 275 and 198 being blocked against further consequent movement by lug 204 on member 198 engaging rack means 191. Elevation of inter-coupled members 330 (FIG. 24) not in "latched position" rocks the related bellcranks 332 counter-clockwise, each actuating its related parts 271, 273, (FIG. 22) 275 and 198 for effecting triggering for a carry operation in the respective order, as described. Thus, carry operations in all consecutive orders still standing at pre-carry are performed substantially simultaneously. The means for swinging couplers 337 (FIG. 24) clockwise to effect coupling with extensions 336 will now be described.

In each order of the entry mechanism, except the lowest and overflow orders where sensing of the pre-carry standing of the related dial is not required, a lever 342 (FIG. 28) is pivotally mounted on movable rod 343 (to be described) which is illustrated in its position for additive operations, and which is moved forwardly a predetermined extent to a position for subtractive operations. Toward its forward end, lever 342 has an elongated slot 344 for slideable support of the lever on relatively stationary stud 345, the slot permitting the lever to be moved forwardly by rod 343 to subtractive position, as illustrated in FIG. 27. Stud 345 is carried by lever 346 (FIG. 28) which is pivotally mounted at its forward end on shaft 268, 75

and the rearward free end of lever 346 underlies rod 281 which, it will be recalled, is elevated (see FIG. 23) at the same time member 328 is turned clockwise. Forward of rod 281, FIG. 28, lever 346 carries a lateral lug 347 which overlies forwardly extending finger 348 of U-shaped member 349 pivotally mounted on rod 281. A spring 350 is fastened to member 349 and shaft 166 for exerting counter-clockwise turning force on finger 348, against lug 347 and therethrough exerting clockwise turning force on lever 346 against rod 281. A second U-shaped member 351 is pivoted on rod 281 (FIG. 26) so that the transverse portion of member 351 and the corresponding portion of member 349 are in contact relation with each other. Torsion spring 352 fastened to members 349 and 351 yieldably holds the members together for constraining member 351 (FIG. 28) to rotate clockwise with member 349, as will be described. Member 351 is formed with a depending finger 353 in the path of clockwise movement of which stands the afore mentioned lug 341 (FIG. 24) on coupler 337. At the same time rod 281 is elevated, spring influenced member 349 (FIG. 28) thereon carries the related levers 342 and 346 normally upwardly. Full upward movement of levers 342 and 346 is blocked, as will be described, when the related dial stands at pre-carry. Consequently, lug 347 on lever 346 causes member 349, and the thereto yieldably constrained member 351, to rotate clockwise on rod 281 against the tension of spring 350, as the rod completes its upward movement. At such times, finger 353 (FIG. 24) on member 351 engages lug 341 and therethrough swings coupler 337 into engagement with extension 336 of the adjacent lower order member 330. If, however, the dial is at other than pre-carry, the upward movement of related levers 342 (FIG. 28) and 346 will not be blocked. Consequently, members 349 and 351 will not be rotated clockwise and the related member 330 (FIG. 24) will not be coupled to the adjacent lower order member 330.

Lever 342 (FIG. 27) has pivoted thereon sensing member 354 which is held yieldably in its normal position, as illustrated, by means of torsion type spring 355, mounted on stud 356 on the lever, which spring is tensioned against rod 343 and the underside of the sensing member 354. Each gear 221 (FIG. 28) has secured thereto a member 357 carrying four lateral lugs 358, spaced equi-angularly relative to the axis of shaft 222, and spaced equally radially therefrom. The relationship between sensing member 354 and ordinarily related member 357 is such that when the related dial stands at pre-carry, one of the four lugs 358 (the ratio between gear 221 and the dial being 4 to 1) stands in the path of upward movement of the sensing member 354, thereby to block levers 342 and 346 against moving upwardly fully. A lug 358 shown in phantom is standing in the path of member 354 as during additive operations. In the event a dial is not at pre-carry, but is turned to that standing while the sensing member 354 is in its uppermost position, member 354 will be in the path of the pertinent lug 358, which will then cant the member clockwise or counter-clockwise against the tension of spring 355, depending on whether the entry operation is additive or subtractive respectively. Upon return of the canted member 354 downward, tensioned spring 355 will turn the member back to its normal position.

With respect to simultaneous triggering: Should the blocking lug 358 be moved out of the path of member 354, finger 353 will be turned counter-clockwise by means of spring 350, and coupler 337 (FIG. 24) will disengage from the adjacent lower order extension 336, providing elevation of member 330 of that adjacent lower order from "latched position" has not started. The member 330 carrying the coupler 337 so disengaged will then be latched onto its related finger 329. If the adjacent lower order member 330 started to elevate as the engaging influence of finger 353 is removed from coupler 337, extension 336 of the lower order member 330 presses against the engaging portion of coupler 337 sufficiently to frictionally hold the coupler engaged therewith. Thus, the occurrence of loss of an order for triggering for simultaneous carry, or of an improper, unwanted carry in an order is not possible.

Rod 343 (FIG. 14) is secured at its left end portion to upright lever 359, pivoted on support unit member 164, and is secured at its right end portion to companion lever 360, FIG. 13, pivoted on support unit member 165. Link 361 is pivotally connected to the right end portion of rod 343 and to the depending arm of bellcrank 226, and link 362 (FIG. 14) is pivotally connected to the left end portion of rod 343 and to the depending arm of bellcrank 230 for moving rod 343 forwardly from additive operating position to subtractive operating position when rod 218, carried by the bellcranks is moved downwardly for subtractive entry operations, as described. Thus sensing members 354 (FIG. 28) are carried forwardly to sensing position for subtractive operations, as illustrated in phantom.

8. CARRY MECHANISM FOR OUTBOARD PRODUCT REGISTER ORDERS

In FIGS. 1 and 2 of the illustrated embodiment, the 12th to 20th orders, inclusive, of register 3 may be outboard orders and the 21st order is always outboard. A carry mechanism is provided for operating only the outboard orders of the register, thereby to enable utilization of the register to its capacity. This capacity or outboard carry mechanism is substantially the same in each order, hence the description of the mechanism in one order and of its inter-relation with the mechanism of the adjacent order will also describe the mechanisms in the other orders and the inter-relation therebetween.

A reciprocatory transfer actuator lever 363 (FIG. 29) for each outboard register wheel is pivotally mounted on shaft 364, transverse the 12th to 21st order compartments of the carriage and secured to the frame thereof. The counter-clockwise influence of return direction spring 365, fastened to lever 363 and the carriage frame, normally holds the lever in rest position with its generally upright extension on the free end thereof against stop rod 366, which is transverse the 12th to 21st sections and is secured to the carriage frame. Member 367, FIG. 30, formed of a forwardly extending arm and a depending arm, is pivoted on shaft 364 in proximity to lever 363 with the free end of the forward arm of member 367 overlying lateral lug 368 carried by the lever. Torsion spring 369, between the member 367 and the lever 363, yieldably holds the member against the lug for constraining member 367 to turn clockwise together with lever 363 until the depending arm of the member moves against sleeved shaft 370 carried on the carriage frame.

Drive pawl 371, shown in FIGS. 30 and 31, is pivoted on the free end portion of the forward arm of member 367 for effecting turning of its related dial for a carry of "1" when the member is turned clockwise or downward its limited angular extent. Pawl 371 is formed of an upright extension and rearwardly and forwardly situated depending arms which on their free ends carry lateral lugs 372 and 373 respectively. Spring 374 is fastened to pawl 371 and to member 367 for constraining the pawl counter-clockwise with its upright arm against rod 375. The rod, as will be described more fully, is movable forwardly a predetermined extent from its additive position (shown in phantom in FIG. 31) to subtractive position for accordingly moving pawl 371 clockwise from its normal additive position to subtractive position against the tension of spring 374. The arrangement is such that in additive position of pawl 371, FIGS. 30 and 32, its lug 372 is in engaging alignment with gear 221, and in subtractive position of the pawl, its lug 373 (FIG. 31) is in engaging alignment with gear 221. In each instance, when the pawl is moved downwardly a predetermined extent, the effective lug engages the teeth on the gear for turning the same only sufficiently to effect carry turning clockwise of the related dial 8 (FIG. 32) for additive operations and counter-clockwise for subtractive operations. During the downward and the subsequent return strokes of pawl 371, the rod contacting face 376 (FIG. 31) of the pawl extension is so contoured as to guide the pawl for preventing binding of its lugs 372 and 373 with the teeth of gear 221. Over-rotation of a

gear 221 in response to actuation by one of the lugs 372 and 373 is blocked by the other one of the lugs which engages the gear teeth in the final phase of the downward movement of pawl 371, thereby to oppose any further rotation of the gear by the effective lug.

Coupling means are provided for intercoupling of the just described dial carry actuating means of one order with the dial actuating means of the adjacent lower order when the dial of that lower order stands at "pre-carry." The purpose of such inter-coupling of two or more orders is to effect motivation at the same time of all outboard order dial carry actuating means successively inter-coupled to the first outboard order actuating means when the actuating means of that first outboard order is motivated for carry operation. In each order 13 to 21, inclusive, a coupling member 377 (FIG. 33) is pivotally mounted on stud 378 on the forward portion of lever 363, and is formed with a lateral lug 379 which extends rightward toward lever 363 of the adjacent lower order, through opening 380 on the intervening carriage compartment plate 46. A torsion spring 381 is coiled about stud 378 and is fastened to member 337 and lever 363 for exerting counter-clockwise turning force on the member for holding it in normal or rest position with its lug 379 against plate 46 in the opening 380. Each lever 363 (FIGS. 34 and 35) is formed with a lateral lug 382 extending leftward so as to be engageable by lug 379 of the adjacent higher order upon clockwise movement thereof under lug 382. In rest position lug 379 stands rearward, clear of the path of downward movement of lug 382. As will be described presently, sensing means is provided in each order for swinging lug 379 of the adjacent higher order clockwise into the path of lug 382 of that order when the dial of that lower order stands at pre-carry, and for swinging the lug 379 forward of lug 382, out of the path of downward movement of lug 382, when that lower order dial stands at other than pre-carry, as denoted respectively by "Rest," "Carry" and "No Carry" graph therefor in FIG. 34. Thus, the respective levers 363 of two adjacent orders are inter-coupled only when the dial of the lower order stands at pre-carry; then subsequent actuation of the lower order lever 363 moves the higher order lever 363, whereby carry is effected in both such orders substantially at the same time. If the dial in the lower of two adjacent orders stands at other than pre-carry, the related levers 363 are not inter-coupled and actuation of the lower order lever will not move the higher order lever.

In each order 12 to 20 inclusive, FIGS. 34 and 35, a lever 383 is pivotally mounted on transverse shaft 384 which is secured on the carriage frame. The rearward arm of lever 383 is formed with lateral lug 385 which contacts lug 379 of the adjacent higher order for swinging lug 379 clockwise from "rest" position to its coupling or "carry" and non-coupling or "no carry" positions (as denoted in FIG. 34) when lever 383 is turned clockwise. Torsion spring 386 is fastened to lever 383 and to rod 387 for constraining the lever clockwise, so that its rearward arm contacts the transverse rod 387 for movement therewith. Rod 387, as will be described later, is movable forwardly, as indicated in phantom, as limited by slot 388 (FIG. 29) on each compartment plate 46 between orders 12 to 20 inclusive, through which the rod extends.

A depending member 389, FIGS. 34 and 35 pivotally mounted on the free end of the forward arm of each lever 383, carries stud 390 on its free end portion. Stud 390 is received in V-notch 391 on the free end of lever 392 which overlies the stud and is pivoted at its rearward end on movable transverse rod 393. Torsion spring 394, FIG. 34 fastened to lever 392 and rod 393, influences the lever clockwise against the stud 390 for movement of member 389 clockwise from its illustrated sensing position in additive operations to its subtractive operation sensing position, shown in phantom. Spring tensioned lever 392 also guides member 389 during its downward movement from "Rest" position for sensing the "Carry" or "No Carry" standing of the respective dial as denoted. Rod 393 extends through orders 12 to 20 inclusive and, as will be described, is normally held in additive position against plates

46 (FIG. 29) at the forward end of slot 395 on each plate, and is moved rearwardly, as limited by the slot, for swinging members 389 (FIG. 34) clockwise to subtractive position shown in phantom. Member 389 depends toward the afore described member 357, which is illustrated in a position relative to the pre-carry standing of the associated dial during additive operations. The position of member 357 relative to the pre-carry standing of the related dial in subtractive operations is denoted by its lugs 358 shown in phantom in FIG. 34. The relationship between members 357 and 389 is such that when the related dial stands at pre-carry one of the four lugs 358 on member 357 stands in the path of downward movement of member 389, allowing member 389 to move only sufficiently to effect coupling between lug 382 of that order and lug 379 of the adjacent higher order, as described. The blocking of member 389 by a lug 358 occurs substantially midway in the forward movement of rod 387 which continues its movement against the tension of spring 386, as limited by slot 388, FIG. 29. Thus, levers 363 (FIG. 35) of successive orders may be inter-coupled by the related members 377 and clockwise actuation of the lowest order of the inter-coupled levers will also move the others of the levers inter-coupled therewith, for effecting carry operations in all orders so inter-coupled. If the dial in one order does not stand at pre-carry, none of the lugs 358 FIG. 34) of the related member 357 stand in the path of member 389, hence lug 379 of the adjacent higher order is swung clockwise sufficiently to be out of the path of lug 382 of that lower order lever 363. Consequently, actuation of that lower order lever 363 will not effect movement of the adjacent higher order lever 363 or of any other lever 363 that may be successively inter-coupled with that higher order lever 363.

The coupled relation between lug 379 of one order and lug 382 of the adjacent lower order cannot be lost while a carry operation is being performed in that lower order. By the time the carry operation would cause the effective lug 358 of the related member 357 to move out of the path of member 389, (Whereupon lever 383 would be free to complete its clockwise stroke and thus possibly move lug 379 clear of lug 382,) the lug 379 (FIG. 33) will have moved downwardly sufficiently in the opening 380 therefor so as to be blocked by plate 46 from being moved out of coupled relation. In the lower portions of opening 380, plate 46 is contoured to conform to the arcuate path of lug 379 as it is moved downwardly about the axis of shaft 364.

Referring to FIG. 34, the spring influenced V-notch coupling between lever 392 and stud 390 is such as to allow member 389 to be canted from its normal depending position when the member is in its lowest position (the related dial then standing at other than pre-carry), and through a carry operation in that order one of the lugs 358 of member 357 moves to pre-carry position, with member 392 then being in its path. On return movement of lever 383 counter-clockwise, notch 391 coacts with lug 390, under the influence of spring 394 for re-adjusting member 389 to the same depending position it was in before canting occurred.

It will now be described how the first outboard order carry means is actuated to effect a carry in that order, (and in all higher orders having their levers 363 successively coupled to the first outboard lever 363) when the highest inboard order dial requires that a carry be performed in the first outboard order. In each order 12 to 21, inclusive, a normally disabled coupling means depending hook 396, (FIG. 21) is pivoted on lever 363. Tensioned spring 397 is fastened to hook 396 and lever 363 for turning the hook clockwise for engaging the hook onto actuating rod 398 which extends from the 11th order section to the leftmost section in the carriage. Normally, the hook 396 is not latched onto rod 398 as shown in FIG. 29, and, as the rod moves downwardly away from the lever 363 during a forward stroke of the rod as will be explained, the lever is not operated, but it is held in its normal position by return direction spring 365. Normally, hook 396 is held out of engagement with rod 398 by means of its lug 399 being latched onto lug 400 on the free end of detent 401 pivoted on

carriage frame shaft 50. Torsion spring 402 (FIG. 29) is fastened to detent 401 and to frame 46, for urging the detent counter-clockwise to engage its lug 400 with lug 399 of hook 396, and to yieldably hold the detent against lateral lug 403 on the left arm of U-shaped member 404. Member 404, pivoted on shaft 50, extends rightward under the intervening frame 46 to the adjacent lower order section, where the right arm of member 404 (FIG. 21) is secured to lever member 261 which, previously described in connection with carry mechanisms of the main body, is rocked clockwise each time its related dial turns through tens carry in either additive operations or subtractive operations.

Hence, each time a dial passes through tens carry, detent 401 in the adjacent higher order is turned clockwise for disengaging its lug 400 from lug 399 of hook 396 for allowing the spring tensioned hook to turn clockwise for engaging actuating rod 398, as shown in phantom in FIG. 33, when the rod is in "hook-engaging" position, as shown. The lever 363 so coupled to rod 398 and all higher order levers 363 successively coupled to the first mentioned lever 363, as previously described, will be turned clockwise from normal position by the substantially downward movement of rod 398, in a forward stroke of the rod.

Effective encouplement of a lever 363 with rod 398, as just described, will occur only in that order which is currently the first outboard order. Hooks 396 of orders that are (at times) inboard are blocked from latching onto rod 398, as will be described. Hooks 396 of successively inter-coupled higher outboard orders will, be triggered in response to the carry operation in the respective adjacent lower orders, and, as a result, these hooks may engage with the actuating rod, since the related levers 363 maintain substantially the same angular relation to rod 398 as the latched first outboard order lever 363, through the successive inter-coupling of the levers. Such latching of the higher order hooks 396 with rod 398 are of no consequence, the related levers 363 then being substantially actuated by the first outboard lever 363. If it should occur that rod 398 is displaced downwardly from inter-coupled higher order levers 363 as compared to the displacement between the first outboard lever 363 and rod 398, the leading faces 405 of triggered hooks 396 will contact the rod, as shown in phantom. Such displacement, if any, is not sufficient to permit a triggered hook 396 to swing over the rod. Downward from "hook engaging position" to the limit of its stroke, rod 398 is always in the path of faces 405. On its return stroke, the rod 398 moves upward, as will be explained, toward the levers 363. During the return stroke of rod 398, it performs two distinct restoring functions, namely restoring the triggered hooks 396 and positively assuring that the operated levers are restored to normal position as shown in FIG. 29. As the rod 398 moves upwardly in its return stroke from the position indicated in phantom in FIG. 33, all actuated hooks 396 and levers 363 are released to whatever returning action their light tensioned springs 365 (FIG. 29) may have. However, the springs 365 are not relied upon for positive return force. At some point in the return stroke of rod 398, the rod 398 moves away from the latching surface of hooks 396, and it coacts with cam surfaces 406 (FIG. 33) of any triggered hooks for rocking and relatching them with their respective detents 401 (FIG. 29). As shown here, the rod 398 in its final uppermost extent of its return stroke has relatched the hook 396 and it has engaged the lever 363 for assuring that the actuator is fully restored, in fact since the rod is transverse to all actuators it assures that all actuators are positively restored to the position shown.

At times orders 12 to 20, inclusive, may be inboard. Hooks 396 of these orders are formed with depending, rearwardly extending fingers 407, FIG. 33, and a transverse member 408 (FIGS. 14 and 23) carried by the support unit stands in the path of clockwise movement of only inboard fingers 407 for blocking hooks 363 from latching on to rod 398. Referring to FIGS. 14 and 23, it will be recalled that the support unit is elevated at the start of computation operations. Hence, member 408 is elevated from normal position into the path of

inboard fingers, as shown in phantom in FIG. 33. By the time transverse member 408 is moved down to normal position again, rod 398 will have moved downwardly from "hook engaging" position, whereat the rod blocks a triggered hook 396 from latching thereon. Therefore, inboard orders of the capacity carry mechanisms are not actuated for effecting carry operations. Only hook 396 of any first outboard order is the lowest order hook which may be latched onto rod 398 in response to turning of the dial in the adjacent lower order (the highest inboard order) through tens carry by the entry and carry mechanism of the main body.

9. ACTUATING AND SUBTRACTIVE OPERATION SETTING MEANS FOR OUT-BOARD CARRY MECHANISM

The motivating means provided for moving actuating rods 387 (FIG. 29) and 398 will now be described. A shaft 409, journaled on the carriage frame, extends from the leftmost to the 11th compartment through suitable openings on the intervening compartment plates 46. Forwardly extending companion levers 410 (FIG. 36) and 411 are secured respectively to the left and right end portions of shaft 409. Depending links 412 and 413 are pivotally connected respectively on the free ends of levers 410 and 411 and at their other ends links 412 and 413 are pivotally connected respectively to the free ends of levers 414 and 415 which are pivoted on shaft 364. The left portion of shaft 409 has secured thereto gear segment 416 which is meshed with gear segment 417 on shaft means 418 which, as will be described later, is a telescoping arrangement for operating the carriage borne carry mechanism in any position of the carriage, a part of the arrangement being secured to the carriage frame for traverse movement therewith and the other part being secured to the stationary main frame, for, among other operations, transmitting turning force from the multiplying power unit to gear segment 416 for turning the same clockwise, thereby effecting clockwise turning of levers 414 and 415. A torsion spring 419 is fastened to lever 410 and the carriage frame for turning counter-clockwise the unit formed of parts 409 to 416 inclusive. levers 414 and 415 are formed respectively with lateral lugs 420 and 421 on their forward ends and with substantially upright fingers 422 and 423 on their pivotal end portions. Furcated companion members 424 and 425 are pivoted on shaft 364, with member 424 situated rightward of lever 414 so that its upper furcation 426 overlies lug 420 of the lever, and with member 425 situated leftward of lever 415 so that its upper furcation 427 overlies lug 421 of lever 415. Actuating rod 398 is fastened at its left and right ends respectively to the lower furcations 428 and 429 of members 424 and 425. Under the influence of spring 419, lugs 420 and 421 hold the parts 398, 424 and 425 normally at the position shown, with rod 398 (FIG. 29) contacting plates 46 at the upper end of slots 430 thereon through which the rod extends. This position of rod 398 is its afore described "relatching" position, in which position the rod 398 normally occupies for relatching the hooks as described and for assuring that the actuators and their lugs 372 and 373 (FIG. 30) on drive pawls 371 are in normal position, clear of conflict with the gears 221, between cycles of the multiplying power unit and at all times except when the drive rod 398 is moved downward from normal position to permit and effect carry operations. By referring to FIGS. 29-31, it is obviously imperative that the rod 398 assure positive restoration and maintenance of the actuators in normal position, since there must not be conflict of the lugs 372 and 373 (FIG. 30) with the teeth of gears 221, particularly at the time when the rod 375 may shift the drive pawls from plus to minus position (FIG. 31) and vice-versa, as explained.

A pair of centralizing levers 431 (FIG. 36) and 432 are pivoted on shaft 364 in proximity to each other and extend forwardly with lever 432 extending under rod 398 and stationary shaft 433 secured on the carriage frame, and with

lever 431 extending over the rod and shaft. A torsion spring 434 between levers 431 and 432 of lesser tension than spring 419 constrains the levers counter-clockwise and clockwise respectively, with lever 432 (FIG. 37) contacting stop shaft 433 and with lever 431 contacting rod 398. Thus, when levers 414 and 415 (FIG. 36) are turned clockwise, spring-constrained lever 431 (FIG. 37) moves rod 398 downwardly following in unison with levers 414 and 415 until lever 431 contacts stop shaft 433, as shown in phantom in FIG. 37, and levers 431 and 432 temporarily arrest rod 498 at this position, which is the afore described "hook engaging" position of the rod. This temporary arrest of rod 398 is made possible by the lost motion provided between lugs 420 (FIG. 36) and 421 on levers 414 and 415 and the related lever furcations 428 and 429 on levers 424 and 425. During the interim lugs 420 and 421 move away from the upper furcations and contact the lower furcations, rod 387 (FIG. 34) is actuated for effecting pre-carry sensing and inter-coupling, as described. Then rod 398 (FIG. 37) is moved downward from its "hook-engaging" position for effecting carry, as described.

Rod 387 (FIG. 36) is pivotally mounted at its left and right ends on the free ends of generally upright levers 435 and 436 respectively, which are pivoted on shaft 384. Links 437 and 438 are pivotally connected to left and right portions respectively of rod 387 and extend rearward where they are connected pivotally to the free ends of generally upright levers 439 and 440 respectively, which are pivoted on shaft 364 in proximity to levers 414 and 415 respectively. Levers 441 and 442, formed with lateral lugs 443 and 444 respectively, are pivoted on shaft 364 in proximity to levers 414 and 415 respectively on the opposite sides thereof from levers 439 and 440. The arrangement is such that lug 443 extends into the path of clockwise movement of lever 439 and of finger 422 on lever 414, and likewise, lug 444 extends into the path of clockwise movement of lever 440 and of finger 423 on lever 415. A torsion spring 445 is fastened to lever 439 and to lug 443, and a torsion spring 446 is fastened to lever 440 and to lug 444 for yieldably holding levers 439 and 440 to their related lugs 443 and 444. A torsion spring 447 between levers 414 and 441 and torsion spring 448 between levers 415 and 442 constrains the levers for yieldably holding fingers 422 and 423 and the respectively related lugs 443 and 444 together. In normal or rest position, the fingers 422 and 423 are displaced counter-clockwise from the related lugs 443 and 444, as illustrated in FIG. 38 of finger 422 and lug 443, in which position the counter-clockwise influence of springs 447 (FIG. 36) and 448 respectively on levers 441 and 442 holds rod 387 against plates 46 (FIG. 29) at the rearward end of slots 388 thereon. When rod 398 (FIG. 36) moves into its "hook-engaging" position fingers 422 and 432 contact their related lugs and, while rod 398 is temporarily arrested thereat, levers 441 and 442 are turned clockwise together by the fingers. Consequently, spring constrained levers 439 and 440 are turned clockwise with levers 441 and 442 for effecting forward movement of rod 387 as limited by slots 388, FIG. 29. When forward movement of rod 387 is thus arrested, lugs 420 (FIG. 36) and 421 contact lower furcations 428 and 429 and springs 445 and 446 yield, allowing levers 414 and 415 to continue their clockwise movement for moving rod 398 downward from its "hook-engaging" position for effecting carry operations, as described.

A bellcrank 449 is secured to the right end portion of journaled tubular shaft 450 of telescoping means 418. The upper end of link 451, is pivotally connected to the free end of rearwardly extending arm of bellcrank 449 and its depending end is turnably mounted on stud 452 (FIG. 40) on the free end of lever 453 pivoted on stud 454 on the machine frame. Return torsion spring 455 is fastened to bellcrank 449 and the machine frame for urging the depending arm of bellcrank 449 counter-clockwise, against stop stud 456 on the machine frame, thereby normally holding parts (FIG. 36) 416, 417, 449, 451 and 453 (FIG. 40) in rest position. Member 457 is formed with notch 458 on its upper end for normally engaging stud 452, and is pivotally mounted at its lower end on follower

459 which is pivoted on shaft 103. Spring 460, fastened to member 457 and the machine frame, constrains member 457 clockwise to yieldably hold the member engaged with stud 452, and torsion spring 461, fastened to follower 459 and the machine frame, urges the follower clockwise so that roller 462 mounted thereon, at all times contacts the periphery of cam 69. The periphery of cam 69 is such that in the initial phase of its clockwise revolution follower 459 is moved counter-clockwise sufficiently to effect moving of rod 398 (FIG. 37) from "relatching" to "hook engaging" position, as indicated by the legends on the view, and that after the entry and carry mechanisms of the main body are actuated, follower 459 (FIG. 40) is moved further counter-clockwise for moving rod 387 (FIG. 38) to effect carry sensing and intercoupling and for thereupon moving rod 398 (FIG. 37) to effect carry. Cam 69 (FIG. 40) then allows spring 461 to move the follower clockwise, back to rest position.

The capacity carry mechanism is thus actuated to perform carry in outboard orders of the product register once in each revolution of the multiplying power unit, except when the unit is cycled for division computations. During division operations member 457 is uncoupled from stud 452 automatically, as described in the parent application, and is coupled with a member of the eliminated dividend mechanism for actuating the same.

Actuation of rod 393 (FIG. 34) for shifting members 389 from additive to subtractive pre-carry sensing position, and of rod 375 (FIG. 31) for swinging pawls 371 from additive to subtractive drive position, will now be described. Shaft 463, FIG. 29, journaled on the carriage frame in the leftmost and 11th order compartments, extends through openings 464 on the intervening compartment plates 46. Secured to the left and right portions of shaft 463, FIG. 32, are depending companion levers 465 and 466 respectively, on which rod 393 is secured so as to be substantially parallel with shaft 463. Links 467 and 468 pivotally connected to the free end of levers 465 and 466 respectively, extend forwardly and are pivotally connected respectively to the depending arms of companion bellcranks 469 and 470 which are pivoted on the carriage frame. The generally upright arms of bellcrank 469 and 470 have secured thereto rod 375. Thus, on clockwise rotation of shaft 463 rod 393 is moved generally rearwardly to subtractive position as limited by plates 46 at the rearward end of slots 395, FIG. 29, and rod 375 is moved forwardly to subtractive position as limited by plates 46 at the forward end of slots 471. Return torsion spring 472, FIG. 39, between lever 465 and the carriage frame, returns parts (FIG. 32) 375, 393, 463, 465-470 inclusive, to their illustrated rest or additive position as limited by rods 393 and 375 against plates 46 as described. For turning shaft 463 (FIG. 39) clockwise, a gear segment 473 is secured to the left portion thereof, which gear segment is meshed with gear segment 474 secured to journaled shaft 475 of telescoping shaft means 476 (to be described). On a rightward portion of shaft 475 depending lever 477 is mounted thereon for turning together therewith. The free end of lever 477 is formed with lateral lug 478 which stands in the path of clockwise movement of the free end of lever 359, as shown in phantom, during computation cycling. Lever 359 (FIG. 14) is pivoted on support unit member 164, and when the unit is elevated, as described, lever 359 is moved into contact engagement with lug 478. Consequently, when lever 359 is turned clockwise, as described, lever 477 (FIG. 39) and shaft 475 are turned counter-clockwise for turning shaft 463 clockwise sufficiently to effect setting of the outboard carry mechanism for subtractive operations.

10. TELESCOPING SHAFT MEANS

Two telescoping shaft means 418 and 476 shown respectively in FIG. 41 and FIG. 42, are provided for transmitting turning forces from motivating means in the main machine body to carriage borne mechanisms for actuating the same. Each telescoping shaft means is devised for transmitting two

independent turning forces, each for actuating a different mechanism in the carriage. Through shaft means 418 the outboard carry mechanism (described hereinbefore) and the multiplier register zeroizing mechanism as described in the parent application are actuated, and through shaft means 476 the outboard carry mechanism is changed from additive to subtractive operations, as described hereinbefore, and the product register zeroizing mechanism is actuated, as described in the parent application.

As may be viewed in FIG. 41, shaft means 418 may be constructed and arranged in one preferred form as follows: An elongated rod 479, which is square in cross section, has an elongated bearing 480 removably secured to its left end, as by pin 481. Bearing 480 extends rightward on the rod and is formed with annular flange 482 generally intermediate its ends. The rightward portion of bearing 480 is rotatably received in bushing 483 with the left face of the bushing against flange 482. Bushing 483 is formed with annular flange 484 and is secured to carriage frame plate 46 (second from left as viewed in FIG. 3) with flange 484 (FIG. 39) against the left side of the plate. The right faces of bearing 480 (FIG. 41) and bushing 483 are substantially flush with the right side surface of the related plate 46. A collar 485 is removably secured, as by pin 486, to rod 479 so as to be in contact with the right side of plate 46 and with the flush bearing and bushing faces. Thus, the left portion of rod 479 is rotatably supported on the carriage frame and is secured thereto for endwise movement together with the carriage. The afore described gear segment 417 is secured to bearing member 480 for turning together therewith.

An elongated bearing 487 on a rightward portion of rod 479 is formed internally to conform to the shape of the rod for slidable endwise movement of the rod therein and for turning of the bearing together with the rod. Bearing 487 is also formed with an annular flange 488 on a rightward portion thereof and is rotatably received at its left portion in bushing 489 with the right face of the bushing against flange 488. Bushing 489 extends through a suitable opening therefor on machine frame member 27 and is removably secured thereto against endwise movement, as by annular flange 490 formed on its left end for contacting the left side surface of plate 27 and by C-shaped spring clip means 491 which is received in a suitable annular groove formed on the bushing so that the clip means is against the right side surface of frame plate 27. Hence, no endwise movement of bushing 489 is possible, and leftward endwise movement of bearing 487 is blocked by the bushing. The illustrated relationship between machine frame plate 27 and the adjacent carriage frame plate 46 is that of the carriage in its rightmost position.

Shaft 450, tubular in cross section for allowing free endwise movement therein of rod 479, is mounted on the right end portion of bearing 487 so that its left end face is against bearing flange 488, and is secured to the bearing 487 in any well known manner for turning together therewith. The right end portion of hollow shaft 450 is rotatably received in bushing 492 which extends through a suitable opening therefor on machine frame plate 30, with flange 493, formed on its left end, contacting the left side surface of the frame plate. The right end face of bushing 492 is in contact with bellcrank 449 which is removably secured to shaft 450, as by means of its boss 494 being pinned to the shaft, so that the bellcrank and shaft turn together. A sleeve 495, against the left end face of bushing 492 is secured on shaft 450, as by pin 496, for blocking rightward endwise movement of the shaft. Between the left end of sleeve 495 and bearing flange 488, an elongated gear segment 497, and bosses 498 and 499 of levers 500 and 501, respectively, are rotatably mounted on shaft 450. Members 497-501 are parts of the zeroizing mechanism for the multiplier register, and are rotatable together as described in the parent application. The train of parts including 417, 449, 450, 479 and 480 are rotatable together as set forth herein, for actuating the outboard carry mechanism in any position of the carriage. The carry mechanism actuating train and the zeroiz-

ing mechanism actuating train are turned independently of each other, each by a different motivating means.

Referring to FIG. 42, shaft means 476, in one preferred form, is devised and arranged as follows: A rod 502, which is square in cross section, has a bearing 503 removably secured to its left end, as by pin 504. Bearing 503 extends rightward along the rod and is formed with annular flange 505 generally intermediate its ends. The rightward portion of bearing 503 is rotatably received in bushing 506, with the left face of the bushing against flange 505. Bushing 506 is formed with annular flange 507 and is secured to carriage frame plate 46 (the second from left as viewed in FIG. 3) with flange 507 (FIG. 37) against the left side of the plate. The right faces of bearing 503 (FIG. 42) and bushing 506 are substantially flush with the right side surface of the related plate 46. Collar 508 is removably secured to rod 502, as by pin 509, so as to be in contact with the right side of plate 46 and the flush bearing and bushing faces. Thus, the left portion of rod 502 is rotatably supported on the carriage frame and is secured thereto for endwise movement of the rod together with the carriage. The afore described gear segment 474 is secured to bearing member 503 in any suitable well known manner for turning together therewith.

Bearing 510, on a right portion of rod 502, is formed internally conformingly with rod 502 for slidable endwise movement of the rod therein and for turning of the bearing together with the rod. Bearing 510 is also formed with annular flange 511 on a rightward portion thereof and is rotatably received at its left end portion in bushing 512 with the right face of the bushing against flange 511. Bushing 512 extends rightward through machine frame member 27 and is removably secured thereto. The bushing is fixed in any well known manner against turning, and is secured against endwise movement as by annular flange 513 formed on its left end contacting the left side of plate 27 and by C-shaped spring clip means 514 which is received in a suitable annular groove formed on the bushing so that the clip means is against the right side of plate 27. Hence, no endwise movement of bushing 512 is possible, and leftward endwise movement of bearing 510 is blocked by the bushing. The afore described member 477 is secured to bearing 510 in any well known manner for turning together therewith. The illustrated relationship between machine frame plate 27 and the adjacent carriage frame plate 46 is that of the carriage in its rightmost position.

Shaft 515, tubular in cross section for allowing free endwise movement therein of rod 502, is secured on the right end portion of bearing 510 for turning together therewith and is blocked against leftward endwise movement by member 477 and bearing flange 511. The right end of shaft 515 is rotatably mounted on bearing 516 which is secured to frame member 517 as by stud 518, FIG. 45, and rightward endwise movement of the shaft is blocked by the frame member. Between frame plate 517 (FIG. 42) and bearing flange 511 an elongated gear segment 519 with a lever 520 secured to its left end, and sleeve 521 are turnably mounted on shaft 515. Parts 519 and 520 are part of the zeroizing mechanism for the product dials, as described in the parent application, and the train of parts 502, 503, 510 and 515 are turnable together, as set forth herein, for effecting changing of the outboard carry mechanism from additive to subtractive operations.

11. MULTIPLIER REGISTER ENTRY MECHANISM

The mechanism for moving selected multiplication elements in opposite directions from neutral position for setting up the appropriate product representations thereon, is disclosed in the parent application and includes transverse rod 522, FIG. 7, which is movable angularly relative to the axis of journaled shaft 130, against a settable positive stop arrangement. Thus, for multiplier values one to four inclusive, rod 522 is moved upwardly respectively one to four angular extents or steps from neutral position and for values five to nine inclusive, the rod is moved downwardly respectively one to

five angular extents from neutral position. A lever member 523 is mounted at its ends on shaft 130 and rod 522 for moving angularly with the rod about the axis of shaft 130. Lateral lug 524 formed on lever 523 stands in the path of clockwise movement of multiplier entry control member 525 (FIG. 43) which is pivotally mounted at 526 on the machine frame. The lug contacting face of member 525 is formed with nine stepped stops 531 to 539 inclusive, one stop individual to each angular position of lug 524. The arrangement is such that on movement from normal or neutral position to a multiplier value position 1 to 9 inclusive, lug 524 stands in the path of a stop 531 to 539 respectively. The engaging stop contacts the lug 524 upon angular movement of member 525 of as many steps clockwise as the value of the multiplier. Thus, for example, when the multiplier is "9," lug 524 stands in the path of stop 539, which contacts the lug upon nine steps of movement of member 525.

Lever 540, pivoted on shaft 180, is connected by link 541 to member 525 so that lever 540 turns clockwise together with member 525. The forward end of multiplier register actuating rack means 542 is pivotally connected to lever 540 so that clockwise turning of the lever moves the rack means rearwardly. A lever 543 is pivotally mounted on shaft 180 between lever 540 and the right arm of bail 206 which is the actuating means for the product entry mechanism, previously described herein. Lever 543 carries two lateral lugs 544 and 545, extending therefrom in opposite directions. Lug 544 is held in contact with lever 540 under the influence of spring 546, fastened to lever 543 and rack means 542 so that when lever 543 is turned counter-clockwise, lever 540 rotates following therewith to move rack means 542 forwardly, back to rest or zero position. Lug 545 is normally in contact with bail 206 so as to prevent clockwise turning of lever 543, ahead of the bail. The arrangement is such that when the bail is rocked rearwardly for effecting product entries, as previously described herein, levers 543 and 540 and member 525 are free to rotate clockwise under the influence of spring 547, which is fastened to member 525 and the machine frame, and which is of lesser strength than spring 546 so as not to cause rotation of 540 in advance of 543. Thus, rack 542 is normally moved rearwardly stepwise until member 525 is stopped by lug 524.

In the event, as for example when a dividend is being entered, it is preferred to prevent entry of the multiplier or item in the register therefor, key 21 may be depressed simultaneously with add key 16, whereupon it is held in operated position by key means, described in the parent application, until the multiplying cycle of operations is completed. The shank of key 21 overlies lateral lug 548 of spring restrained lever 549 pivoted on fixed shaft 550. Depression of the key rocks lever 549 downwardly against spring tension so that its face 551 stands in the path of stud 552 on lever 540, thereby blocking lever 540 and the connected rack means 542 from moving rearwardly. Thus, at such times the multiplier is not entered into the dial entrained with rack means 542.

At its rearward end, rack means 542 (FIG. 44) is furcated and is slidably supported on stud 553 which extends through elongated slot 554 formed on the rack means. The oppositely oriented inner faces of the furcations are formed as racks 555 and 556 for meshing selectively with rotatable gear 557. Rack 555 is normally engaged with gear 557, and rack 556 is disengaged therefrom. Gear 557 is mounted on rod 558 and is secured to gear 559 of larger diameter. An auxiliary plate 560 (FIG. 13) is spaced leftward from and is secured to member 165 of the support unit as by rods 558, 561 and 562 and a shaft 563 is journaled on plate 560 and member 165. Spaced, similar pinion gears 564 and 565 (FIG. 44) are secured to shaft 563 for rotating in unison, and so that pinion gear 565 is meshed with gear 559 and pinion gear 564 stands in engaging alignment with gear 566 of the lowest order inboard dial 7. A gear 566 in each order of the multiplier register is rotatable on shaft 567, fixed on the carriage frame, and is meshed with gear 568 which is secured to dial 7, the gear 568 and dial being rotatably mounted on shaft 569 which is also fixed on the car-

riage frame. Thus, upon elevation of the carrier unit, gear 564 (FIG. 45) meshes with the gear 566 aligned therewith, and for each step of movement rearward of the rack means 542 (FIG. 44) the entrained dial 7, with numerals 0-9 about its periphery, is turned counter-clockwise or additively to display the appropriate multiplier numeral through a suitable aperture on the carriage cover.

For subtractive entry operations, rack means 542 is elevated by means of stud 553 sufficiently to disengage rack 555 from gear 557 and engage rack 556 therewith. Thus, on rearward movement of rack means 542, the direction of rotation of gear 557 and therethrough to the entrained dial 7 is reversed, with the dial rotating clockwise and indicating the complement of the multiplier. The relation between racks 555 and 556 and gear 557 is such that one rack partially engages the gear before the other rack is fully disengaged therefrom.

Stud 553 is secured on the rearward arm of lever 570 (FIG. 45) pivoted on support unit member 165, and is supported in normal or additive position by member 165 (FIG. 13) at the depending end of generally vertical slot 571 thereon. Slot 571 allows stud 553 to be moved upwardly relative to member 165 to elevate rack means 542 (FIG. 44) from additive to subtractive position. An optionally rockable key lever 572 on fixed shaft 550 and protruding from key board plate 40, is formed with a lateral lug 573 on its depending end. In normal or add position of key lever 572, lug 573 is free from engagement with the forward end of lever 570. Thus, when lever 570 (FIG. 45) is carried upwardly by the support unit, stud 553 stands in its normal position under the influence of spring 546 (FIG. 44) on rack means 542. However, when key lever 572 is preset, i.e., rocked counter-clockwise, to a predetermined reversing or subtract position, its lug 573 stands in the path of upward movement of lever 570 with the support unit. Consequently, such upward movement of the forward end of lever 570 is blocked, causing the lever to turn counter-clockwise about its pivot 570a and carry stud 553 upwardly relative to the carrier unit to the upper end of slot 571. Thus stud 553 carries rack means 542 upwardly relative to the carrier unit sufficiently to effect disengagement and engagement respectively of its racks 555 and 556 with gear 557, for subsequent reverse actuation of the then entrained dial 7. With key 572 preset in reverse position, the automatic engagement of the dial actuator with the lowest order inboard dial 7 and the automatic shifting of the actuator from additive to subtractive operation occurs concurrently.

12. MULTIPLIER REGISTER CARRY MECHANISM

In one preferred form, multiplier register 2, FIG. 1, comprises ten orders of dials 7. The dial standing in alignment with "0" on channel member 22 in the lowest or first order inboard dial is, as described, engageable and subsequently actuable by the multiplier entry mechanism. Since there are 10 orders of dials 7, of which the lowest order may be the first inboard order, the carry mechanism mounted on the machine frame, comprises nine orders of similar carry devices for actuating as many orders of dials 7. A second order inboard dial stands in operative relation with the first or lowest order carry device. If the first inboard dial is turned through tens carry, all consecutive adjacent higher orders standing at pre-carry are operated simultaneously by the carry mechanism to appropriately exhibit tens carry in each of such orders and in the next higher order.

As previously explained, in each order of register 2, a gear 566 (FIG. 44) is meshed with gear 568 which is secured to dial 7. It will also be recalled that for additive operations gear 566 is turned clockwise and for subtractive operations it is turned counter-clockwise, with the dial 7 turning respectively counter-clockwise and clockwise, and that the gear ratio between meshed gears 566 and 568 is four to one respectively. A member 574 (FIG. 46) of any suitable flexible material is secured to the carriage frame, and is formed with tines, one for and individual to each gear 568 and is crimped at its end to

conform to the gear teeth and to engage between the same for holding gears 566 and 568 and the related dial in each of the positions to which they may be turned by the entry and the carry mechanisms. Dials 7 (FIG. 48) are cylindrical in structure, with one end of each being open, and may be formed of very thin material. To each dial, except in the highest order, a stiffening member 575 may be secured internally at the closed end of the cylinder for carrying a stud 576 extending toward the open end of the dial for movement therewith about shaft 569 as the axis.

A lever 577, FIG. 45, pivotally mounted on shaft 567 in each dial order, except the highest order, carries a V-shaped lateral lug 578 on its generally forwardly extending arm which situates alongside the open end of the related dial so that the lug 578 extends inwardly into the dial cylinder to stand in the path of movement of stud 576. The rearward arm of lever 577 is formed with a lateral lug 579, and the arm underlies a stop stud 580 provided on adjacent carriage frame member 46. A spring 581 is fastened to lug 579 and stop 580 for influencing lever 577 counter-clockwise against the stop. The arrangement is such that stud 576 is in engaging relation with V-shaped lug 578, at the position shown when the dial stands at pre-carry in subtractive operations, and at the position illustrated in phantom when the dial stands at pre-carry in additive operations. Thus, in each instance, when the dial is subsequently turned through tens carry, stud 576 rocks lever 577 clockwise momentarily. Such actuation of a lever 577, however, is significant only when the respective dial is the first inboard dial, as will become apparent presently.

The carry mechanism assembly comprises left and right frame members 582 (FIG. 3) and 517 respectively, which are secured removably to machine frame plates 24, 28 and 29, FIG. 45, in any convenient manner, and to each other by rods 583 and 584. Shafts 585, 586, 587 and 588 are journaled at their ends on members 582 and 517.

In each order of the carry mechanism, a generally depending lever 589 (FIG. 46) is pivotally mounted on journaled shaft 586. A spring 590 is fastened to lever 589 and rod 583 for influencing the lever counter-clockwise and yieldably holding it at rest position with the integral lever finger against the rod. A pair of scissorlike, gear turning members 591 and 592 are pivotally mounted on the free end of lever 589 at 593. The rearwardly extending arm of member 591 overlies lateral lug 594 formed on the rearward arm of member 592 and bail rod 595 which will be described later. Torsion spring 596, fastened to members 591 and 592, influences member 591 clockwise and member 592 counter-clockwise, holding member 591 and lug 594 yieldably in contact with each other. Spring 597, fastened to the forward arm of member 591 and to the forwardly extending finger of latch member 598, pivoted on lever 589 upward from 593, influences members 591 and 592 clockwise as limited by rod 595 which is shown in position for additive operations. Spring 597 also influences latch member 598 counter-clockwise, but the latch member, as will be described presently, is normally blocked against such rotation beyond the position in which it is shown. The forward ends of members 591 and 592 are formed respectively with lugs 599 and 600. As illustrated, in additive position of the members, lug 599 is in engaging relation with gear 566 standing in ordinal alignment therewith, so that on clockwise rotation of lever 589 (to be described), lug 599 engages gear 566 and turns the same clockwise sufficiently to rotate the related dial to exhibit a carry of "1." Toward the end of the carry stroke of lever 589, lug 600 also engages the respective gear 566 for preventing over-rotation of the same. For subtractive operations, rod 595 is elevated sufficiently to rotate the members 591 and 592 counter-clockwise to a position where lug 600 is in engaging relation with gear 566. Then on the clockwise carry movement of lever 589, lug 600 engages gear 566 and turns the same counter-clockwise to effect a carry of "1," and in the final phase of the operation lug 599 also engages the gear for preventing over-rotation of the same.

Rod 595, extending transverse all orders of the carry mechanism, is secured at its left and right ends respectively to companion levers 601 and 602 (FIG. 47) which are secured to journaled shaft 588. A lever 603, FIG. 45, secured to the right end of shaft 588, is connected by link 604 to key lever 572 so that counter-clockwise movement of key lever 572 to subtract position, turns shaft 588 clockwise thereby to elevate the bail rod. Key lever 572 and rod 595 (FIG. 47) are held yieldably in their additive and subtractive positions by means of lever 605 (FIG. 49) secured to shaft 588 and spring biased detent 606 pivoted at 607 on plate 517. Detent 606 is formed with two spaced cam notches 608 and 609, and the free end of lever 605 carries stud 610 which, in additive position of shaft 588, engages detent 606 in notch 608, and in subtractive position of the parts, stud 610 engages in notch 609. In moving the parts from additive to subtractive position and back again to additive position, according to optional setting of the key therefor, stud 610 rocks detent 606 counter-clockwise against the tension of spring 611 secured thereto and to rod 583. The angular extent of clockwise and counter-clockwise rocking of shaft 588 is limited respectively by edge faces 612 and 613 formed by the notches.

The afore mentioned latches 598 (FIG. 46) extend rearwardly and each is formed with lateral lug 614. Detent 615 (FIG. 47) in the first order and a detent 616 (FIG. 50) in each of the other orders are pivotally mounted on journaled shaft 585 and the depending free end of each detent is formed with a step face 617 for engaging lug 614 of latch 598 of the respective order, for holding the latch in normal or cocked position, against the counter-clockwise influence of spring 597. Clockwise rotation of a detent 615 or 616, as will be described, disengages the same from lug 614, allowing the respective latch 598 to be spring rocked counter-clockwise for engaging shoulder or step face 618, formed on latch 598, with rod 619 which, in one preferred form, is square in cross-section. Thus, when rod 619 is moved forwardly, as will be described, the engaged latch 598 is moved thereby for rocking of the respective lever 589 clockwise to effect carry rotation of the associated register-order, as described.

Each detent 615 (FIG. 47) and 616 (FIG. 50) is tensioned counter-clockwise by a torsion spring 620 which is fastened to the detent and rod 584. In one preferred form, each detent 616 carries a rightwardly extending lateral lug 621 and detent 615 (FIG. 48) carries a rightwardly extending lateral lug 622 at a radius location relative to shaft 585 different from the location of lug 621, FIG. 50. In all other respects, a detent 616 and detent 615 are the same structurally, and the lugs 621 and 622 are provided for therethrough effecting clockwise rocking of the respective detent by means in the adjacent lower order, as will now be described.

Referring to FIG. 47, a bellcrank 623 is pivotally mounted on rod 561 of the support unit, in ordinal relation with the first inboard order member 577. Torsion spring 624, fastened to bellcrank 623 and rod 558, influences the bellcrank clockwise and yieldably holds the bellcrank in normal position, as illustrated, with its forwardly extending arm in contact with overlying lug 625 carried by plate 560.

The arrangement is such that in rest or normal position of the support unit, as seen in FIG. 47, the forwardly extending bellcrank-arm and the generally upwardly extending bellcrank-arm of bellcrank 623 are free from engagement respectively with lug 579 of related member 577 and lug 622 of detent 615 in the adjacent higher order. Still further, the relation between bellcrank 623 and lugs 579 and 622 is such that upon elevation of the support unit, as shown in FIG. 45, the forward bellcrank arm is in engaging relation with lug 579 for being rocked counter-clockwise thereby, and the upright bellcrank arm is in engaging relation with lug 622, for rocking detent 615 counter-clockwise. Thus, when the first inboard order dial 7 is turned through tens carry, member 577 rocks bellcrank 623 sufficiently to disengage detent 615 from latch 598, FIG. 46, whereupon shoulder 618 of the latch engages rod 619 for carry actuation thereby in the second inboard register order.

For disengaging a detent 616 (FIG. 50) from related latch 598, the following means is provided in the adjacent lower order: A generally depending lever 625 (FIG. 51) is pivoted on shaft 586. Toward the free end of the lever, a generally upright member 626 is pivoted at 627 and carries lateral lug 628 for normally contacting the forward edge of lever 625. A spring 629 is fastened to member 626 and to rod 583 for influencing the member clockwise and holding its lug 628 against lever 625 and therethrough holding the lever in normal position with its integral finger contacting rod 583. A depending lever 630 (FIG. 52) is secured to journaled shaft 585 so that the free end of the lever contacts lug 628 for moving the lug, consequent clockwise turning of the shaft a predetermined angular extent, as will be described. Hence, member 626 and therethrough lever 625 are normally turned together clockwise about shaft 586. If the dial of the register order associated with a lever 625 stands at pre-carry, the angular extent of clockwise turning of the lever will be limited; consequently, member 626 will be turned counter-clockwise about its pivot 627 in response to completion of the predetermined extent of movement of lever 630. Lateral lug 621 (FIG. 53) of the adjacent higher order detent 616 stands in the path of counter-clockwise turning of member 626. Thus, at such times, a member 626 rocks the adjacent higher order detent 616 clockwise sufficiently to disengage the same from related latch 598, FIG. 50. If the first inboard order dial turns through tens carry and all other higher order dials stand at pre-carry, latches 598 relative to those higher order dials are freed to engage with rod 619. Then, when rod 619 is moved forwardly, carry is effected in each of such orders simultaneously. If an inboard order dial stands at other than pre-carry, the adjacent higher order detent 616 will not be disengaged, and such a latch blocks engagement of all higher order latches from engaging with rod 619, even though the related detents 616 may be disengaged therefrom, due to the pre-carry standing of the respective register orders. This is accomplished by rightwardly extending offset lateral lugs 631 carried by latches on a rearward portion thereof. Each lug 631, as illustrated in one preferred form in FIG. 54, is offset so that the rightmost portion underlies and contacts the left portion of the adjacent lower order lug 631.

Hence, when a latch 598 is not allowed to turn upwardly, its lug 631 stands in the path of upward movement of the adjacent higher order lug 631, thereby blocking upward movement of that adjacent latch and all other higher order latches 598. The lowest order lug 631 may be formed as illustrated, without the offset extension portion, there being no need for such an extension.

For sensing pre-carry standing of an inboard register order, the following means is provided: A sensing member 632 (FIG. 52) and a rearwardly extending lever 633 (FIG. 51) are pivoted at 634 on the free end of lever 625. Lever 633 overlies rod 595 and is yieldably held thereagainst under the clockwise influence of lightly tensioned spring 635 fastened to the forward end of lever 633 and to lever 625. Spring 635 is of lesser tension than spring 629. Sensing member 632 carries lateral lug 636 on its rearward arm and lateral lug 637 on its forward arm. A spring 638 is fastened to member 632 and lever 633 for urging member 632 counter-clockwise to hold its lug 636 in contact with the overlying lever 633. Thus on elevation of rod 595, lever 633 and sensing member 632 are moved together from the illustrated additive position to subtractive position, as shown in phantom of the forward arm of member 632. A member 639 is secured to each gear 566 for rotation therewith, and each member 639 is formed with four lateral lugs 640 spaced angularly and radially equally relative to the gear axis. The arrangement is such that when a dial 7 (FIG. 45) stands at pre-carry, one of the four lugs 640 (FIG. 51) stands in the path of forward movement of lug 637. Hence, at such a time, full stroke of lever 625 is blocked, effecting counter-clockwise rocking of member 626 for disengaging detent 616 (FIG. 50) from latch 598 in the adjacent higher order, as described. The blocking position of a lug 640 (FIG.

51) relative to the pre-carry standing of the dial in additive operations, is illustrated in phantom. In subtractive operations a blocking lug 640 stands in the path of lug 637 then in the phantom position, as shown.

The latches 598 (FIG. 46) engaged with rod 619 are disengaged therefrom and re-engaged with their respective detents 616 and 615 by transverse rod 641. Latches 598, engaged with rod 619, stand in the path of downward movement of rod 641 which is so moved subsequent to return of rod 619 rearwardly to the position shown. Thus, each of such latches 598 is turned at the same time clockwise sufficiently for the related spring tensioned detent to engage its step face 617 with lug 614 of the latch, thereby to hold the latch in cocked position again. Rod 641 is secured at its right and left ends respectively to the forward free end of levers 642 (FIG. 47) and 643 (FIG. 46) which levers are secured to journaled shaft 587. Hence, counter-clockwise rotation of shaft 587 moves rod 641 generally downwardly, for the recocking operation. For such rotation of shaft 587, a lever 644 (FIG. 55) is secured to its leftmost end. A depending link 645 is pivotally connected to the forward free end of lever 644 and to the rearward arm of bellcrank 646 pivoted on frame plate 27. The generally depending arm of bellcrank 646 is connected by link 647 to upright lever 648 secured to one end of sleeve 649, turnable on shaft 650 fixed on the machine frame. The other end of sleeve 649 has secured thereto a lever 651 which is connected by link 652 to lever 653 so that clockwise rocking of lever 653 swings lever 651 clockwise. Lever 653 is secured to journaled shaft 209. Referring to FIG. 20, it will be recalled that shaft 209 is rotated clockwise during the initial phase of a multiplying cycle of operations before registering operations are performed, and that it is rotated back counter-clockwise after registering and product carry operations are completed. Accordingly, in FIG. 55, shaft 209 is first rotated counter-clockwise and is then rotated back clockwise, and through parts 653, 652, 651, 649, 648, 647, 646, 645 and 644, shaft 587 is rocked counter-clockwise and then clockwise. Hence, rod 641 (FIG. 46) is moved upwardly from its normal or rest position shown in phantom, to the full line position in which it is shown. Then, when all entry and carry operations are completed rod 641 is returned to its rest (phantom) position for recocking latches 598.

The means provided for actuating shaft 585 (FIG. 52) for the sensing operation and rod 619 (FIG. 46) for the carry operation will now be described: Rod 619 is secured at its right and left ends to companion levers 654 and 655 (FIG. 47) respectively. These levers are secured to journaled shaft 586 which is rotated clockwise for moving the rod 619 generally forwardly to effect carry. Such clockwise rotation of shafts 585 and 586 to effect sensing and carry respectively is counter-clockwise in FIGS. 55 and 56. A lever 656, FIG. 56, is secured to shaft 585, and is formed with lateral lug 657 which overlies lever 658 (FIG. 55) pivotally mounted on the shaft. Spring 659, fastened to lug 657 and lever 658, yieldably holds lever 658 against lug 657 so that when lever 658 is moved counter-clockwise lever 656 and shaft 585 rotate together with lever 658, against the influence of return springs 629, FIG. 52. A lever 660 (FIG. 56) is secured to shaft 586, and under the clockwise influence of return torsion spring 661, FIG. 46, fastened to lever 654 and plate 582, lever 660 (FIG. 55) is normally held in contact with stop lug 662 on member 663 secured on plate 582. Lever 660, spaced from and standing in the path of counter-clockwise movement of lateral lug 664 carried by lever 658, is contacted and moved counter-clockwise by lug 654, after 656 has been swung sufficiently to effect the sensing operations.

Under the influence of return springs 629, FIG. 52, through parts 626, 630, 585, 656 (FIG. 55) and 659, lever 658 is normally held in rest position, as illustrated, with integral depending extension 665 contacting lateral lug 666 on lever 667 and influencing lever 667 counter-clockwise against stop stud 668 on plate 582. Stud 668 also stands in the path of counter-clockwise movement of lateral lug 669 on lever 660. Lever 75

667 and a member 670 are pivotally mounted at 671 on plate 582. Torsion spring 672 between lever 667 and member 670 normally holds the lever and member in contact with each other, with finger 673 on the lever overlying and contacting

5 lug 674 carried by the member. A generally upright latch member 675 is pivotally mounted at 676 on support unit member 164. In normal or rest position of the support unit, rearwardly extending finger 677 of latch 675 is in contact with stud 678 on plate 582 so as to hold the latch against the counter-clockwise influence of spring 679 fastened to the latch and member 164. The arrangement is such that on elevation of the support unit, latch 675 is carried upwardly and, at the same time, is swung counter-clockwise by spring 679 into engagement with lug 674 so that subsequent downward movement of the latch will rock member 670 and lever 667 clockwise. As previously described, the support unit is returned downward to rest position after multiplier and product entries and product carry operations are completed. Accordingly, latch 675 then effects rocking of lever 667 for moving lever 658 counter-clockwise until lever 660 is stopped by stud 668. Then spring 672 yields, allowing member 670 to be moved further by latch 675 until the latch is disengaged therefrom, consequent clockwise rocking of the latch effected by the stationary stud 678 situated in the path of downward movement of the latch. Lever 660 is stopped by stud 668 only after the lever has been rotated sufficiently to effect carry operations.

Although I have described a specific embodiment of the invention, it is understood that it is by way of example only, and that various changes may be made in size, shape, materials and arrangement without departing from the spirit and scope of the invention as claimed.

What I Claim is:

1. In a calculating machine comprising a plurality of rotatable ordinal accumulators; a spring biased actuator individual to and for each accumulator for rotating said accumulator to enter numerical values therein, upon movement of said actuator; multiplying means comprising selectively settable partial product stops for each said actuator for differentially limiting movement of said actuator according to the value of the set up partial product stops therefor; each actuator being advanceable relative to any said set-up partial product stop for entering a tens carry in the respective said accumulator; a carry means individual to and for each actuator for normally holding said actuator from advancing relative to its set-up partial product stop, each carry means being operable individually to permit its related actuator to advance under spring bias one step to enter a tens carry in said related accumulator, and a first rockable means individual to each accumulator and the adjacent higher order carry means, and movable from normal position temporarily to operated position by its related said accumulator upon rotation of said accumulator through tens carry position for actuating said adjacent higher order carry means, so that when a consecutive series of said accumulators stand at a pre-carry position, adjacent to said tens carry position, and the next lower order accumulator adjacent to said series is rotated through said tens carry position, a tens carry is entered into each of the accumulators of said series and the adjacent higher order accumulator consecutively; the combination of a second rockable means yieldably connected to said first rockable means for being rockable in advance relative to said first rockable means when said first rockable means is in operated position; and for at all times rocking together with said first rockable means when said first rockable means is not at said operated position; actuating means common to all said second rockable means and being engageable by any said second rockable means upon rocking of said second rockable means by said first rockable means, any second rockable means so engaged with said actuating means holding its said first rockable means at said operated position; a latch means carried by each second rockable means and movable into engagement with the adjacent lower order second rockable means for actuation of the higher order

second rockable means by said adjacent lower order second rockable means; sensing means associated with each accumulator and movable responsible to said pre-carry standing of said accumulator for moving the ordinarily related said latch means to engage said adjacent lower order second rockable means, all higher order second rockable means so inter-coupled with the highest order second rockable means engaged with said actuating means then being rockable in unison by said highest order second rockable means engaged with said actuating means when said actuating means is moved, whereby all said carry means related to said higher order of said second rockable means actuated in unison are operated to effect a tens carry at the same time in the respective orders of said accumulators, and operating means common to all said sensing means and said actuating means for moving all said sensing means in unison and for moving said actuating means subsequent to said movement of all said sensing means.

2. The combination according to claim 1 wherein each said latch means is pivoted on its said second rockable means and is formed with first and second lug engaging faces, a lateral extension carried by each second rockable means for movement therewith and protruding into the path of swing of said latch means relative to its second rockable means in the adjacent higher order, said first face in said higher order engaging said lower order extension when said higher order latch means is rocked by the related said sensing means and said lower order second rockable means is engaged with said actuating means and said higher order second rockable means is in normal position, and said second face engaging said lower order extension when both said higher and adjacent lower order second rockable means are at normal position.

3. The combination according to claim 1 wherein each said second rockable means is formed with a hook projection and said actuating means comprises a pair of spaced coaxially mounted lever means, a bail means in transversely extending relation to all said second rockable means and pivotally mounted at each of its ends on one of said lever means, a tine-member secured to said bail means for movement therewith and formed with spaced, individually flexible tines, one tine for each said second rockable means and normally retracted from contact with its related said hook projection, said bail means being rockable relative to said lever means for contacting and flexing said tines against said hook projections of said second rockable means then in normal position, so that, upon movement of any said second rockable means by its related said first rockable means, the related said tine snaps into engagement with its respective hook projection for said holding of said first rockable means at its said operated position and for moving said second rockable means in advance of said first rockable means when said bail means is moved angularly relative to the axis of said lever means upon rotation of said lever means.

4. The combination according to claim 1 and comprising lug-bearing means individual to each accumulator and rotatable in unison therewith, each accumulator being rotatable in one direction for additive operations and in the opposite direction for subtractive operations, first, second and third transverse rods; said second rod normally in additive position being mounted for radial movement relative to said first rod from said additive position to subtractive position, and said third rod being a part of said operating means and mounted for angular movement relative to said first rod from normal position to operated position; each said sensing means comprising a first lever and a second lever pivoted respectively on said first and second rods and extending toward each other so that the distal portions of said first and second levers are adjacent to each other, said distal portion of said second lever having a lost motion slot means formed thereon, a lateral stud means carried by said first lever and engaging said second lever in said slot means for support of said second lever by said first lever and for angular movement of said second lever from rest position normally to operated position by said first lever, said lost motion slot means also permitting movement of said

second lever by said second rod whenever said second rod is moved from said additive to said subtractive position, a sensing finger pivoted on said second lever and spring restrained in normal position, said sensing finger contracting 5 said lug-bearing means for stopping rotation of said first and second levers at a position substantially midway between the respective said rest position and operated position, whenever said related accumulator stands at pre-carry position, either in additive operations or subtractive operations, said first lever 10 normally contacting said third rod so that said third rod may move angularly in advance of said first lever whenever said first lever is blocked at said midway position, a lateral projection on each first lever, a spring biased rock-member in each order pivoted on said third rod and comprising a first arm normally engaging the related said lateral projection for yieldably 15 holding said first lever in said contact with said third rod for movement of said first lever normally from said rest position to said operated position upon said angular movement of said third rod, said lateral projection causing said rock-member to rotate when said first lever is blocked at said midway position and said third rod advances to its said operated position, said rock-member comprising a second arm engaging the related said latch and moving said latch into engagement with said adjacent lower order second rockable means when said rotation 20 of said rock-member occurs.

5. A calculating machine comprising a series of ordinal accumulator means, differential actuator means operable for actuating said accumulator means, a spring means for each of 30 said series of accumulator means, carry means resiliently biased by said spring means in each order in said series and being triggerable for performing carry operations in each related one of said ordinal accumulator means, means for triggering each of said carry means responsive to actuation of the 35 adjacent lower order accumulator means through tens carry position during operation of said actuator means, so that carry operations in a series of accumulators may be performed consecutively in a crawl-like manner during operation of said actuator means, and a simultaneous carry triggering means 40 operable in sequence immediately following operation of said actuator means for effecting triggering at the same time in a series of orders of carry means in which triggering is to occur and has not yet been performed in the consecutive said crawl-like manner.

6. A calculating machine comprising a plurality of ordinal accumulator means, differential actuator means operable for actuating said accumulator means, a series of crawl carry means for said ordinal accumulator means responsive to operation of the next lower order accumulator means through tens carry for performing a carry in its respective order during operation of said actuator means, and means operable following operation of said actuator means for effecting simultaneous actuation of said series of adjacent orders of said crawl carry means when the associated said accumulator means each stand at pre-carry at the end of the operation of said actuator means and the lowest of said orders of said ordinal accumulator means is operated through a tens carry position.

7. A calculating machine comprising a plurality of rotatable ordinal accumulator means; ordinal accumulator actuator means for each of said accumulator means; a tens carry means for each of said actuator means for advancing said related actuator means for a tens carry in the associated accumulator means and movably responsive to rotation of the adjacent lower order accumulator means through a tens carry position; and simultaneous carry means comprising motivating means common to all said tens carry means, ordinal sensing means all operable together for sensing those associated accumulator means standing at pre-carry position, adjacent to the tens 65 carry position, an actuating means for and engaging each of said tens carry means for operating its tens carry means when the tens carry means is at rest position upon movement of the actuating means, the said actuating means being engageable with said motivating means only at the operated position of the tens carry means and being movable in advance of the tens

carry means in operated position, and a latch means on each of said actuating means movably responsive to the related ordinal sensing means when the associated accumulator means stands at pre-carry position for inter-coupling with the adjacent lower order actuating means, so that all of said actuating means intercoupled in series with the highest order actuating means engaged with said motivating means are all moved together for effecting tens carry in the associated ordinal accumulator means when the highest order actuating means engaged with said motivating means, is moved by said motivating means.

8. A simultaneous carry mechanism for use in a calculating machine in which there is a plurality of rotatable ordinal accumulators means, ordinal accumulator actuators and a tens carry device for each accumulator actuator for advancing the actuator for a tens carry in the associated accumulator and movably responsive to rotation of the adjacent lower order accumulator through tens carry position, said simultaneous carry mechanism comprising motivating means for and common to all said tens carry devices, ordinal sensing means all operable together for sensing the associated accumulator means standing at pre-carry position, adjacent to the tens carry position, an actuating means for and engaging each tens carry device for operating its tens carry device when the tens carry device is at rest position upon movement of the actuating means, said actuating means being engageable with the said motivating means only at the operated position of the tens carry device and being movable in advance of the tens carry device in operated position, and a latch means on each actuating means movably responsive to the related sensing means when the associated accumulator means stands at pre-carry position for inter-coupling with the adjacent lower order actuating means, so that all said actuating means inter-coupled in series with the highest order actuating means engaged with the motivating means are all moved together for effecting tens carry in the associated accumulator means when the highest order actuating means which is engaged with the motivating means is moved by the motivating means.

9. In a calculating machine, the combination of a calculating means for producing the product of a multiplicand and a multiplier, a plurality of register means operable for indicating products, ordinal actuator means comprising tens carry means operable for registering said product under control of said calculating means and for performing any incidental carry operations at the same time in said register means, simultaneous carry means for operating said tens carry means to complete simultaneously any remaining incidental uncompleted consecutive carry after the operation of said actuator means in consecutive registers standing at pre-carry wherein carry should occur, and motivating means for operating said actuator means to register the product and incidental carries and thereafter operating said simultaneous carry means for completing any remaining consecutive carry simultaneously.

10. In a calculating machine, a plurality of register means, carry trip means carried by each of said register means and movable therewith, actuator means for operating said register means under control by said machine, and extendable for performing tens carry registration, incidental carry means carried by said actuator means operable for extending said actuator means, unitarily to include said tens carry registration with the operation of said register means by said actuator means, and inter-connecting linkage means connecting between a said carry trip means and the next higher order said incidental carry means and responsive to tens carry movement of its respective said carry trip means for operating the next higher order said incidental carry means, and whereby when one of said register means, operated by its related actuator means, moves through a carry station, said carry trip means carried by the one of said register means, operates its related inter-connecting linkage means and the next higher order incidental carry means for advancing its actuator means one unit, so as to carry one in the next higher order register means.

11. A calculating machine comprising calculating means for producing a product of a multiplicand and a multiplier, a plurality of ordinarily disposed registers for entry of said product therein, carry trip means carried by said registers and movable therewith, a plurality of actuator means one for and engaging each of said registers for operating said registers, incidental carry means carried by said actuators and operable more than once in each computation cycle for extending said actuators one incremental value for each operation of said carry means, interconnecting linkage means connecting between said carry trip means and the next higher order said incidental carry means and responsive to tens carry movement of its respective said carry trip means for operating the next higher order said incidental carry means, whereby a register in one order is operated through tens carry more than once will cause the next higher actuator means to be extended a corresponding number of increments and resulting operation of said higher order register.

12. An outboard carry mechanism for a calculating machine comprising an ordinally shiftable carriage, a series of ordinal accumulators carried by said carriage, a group of successive orders of said accumulators being inboard and all others being outboard relative to said machine, each accumulator being operable individually according to digit values, a plurality of ordinarily disposed accumulator actuators in said machine operable for entering digit values into all said inboard accumulators, and an inboard carry mechanism for effecting tens carry operation in inboard orders of said accumulators, said

10 outboard carry mechanism being carried by said carriage and comprising similar carry units, one for each order of said accumulators that can be carried outboard, an operating device comprising a movable transverse member common to and for all said carry units, each carry unit comprising first and second

15 coaxial levers, said second lever being yieldably constrained to rotate together with said first lever until said second lever is stopped, whereupon said first lever is movable further angularly relative to said second lever, pawl means carried by said second lever for engaging and operating the related said accumulator for a tens carry upon rotation of said second lever, spring biased latch means carried by said first lever and movable relative to said first lever into engagement with said transverse member under the influence of said spring bias for subsequent angular movement of said first and second levers by

20 movement of said transverse member, a rockable detent means contacting said latch means for normally holding said latch means disengaged from said member, and a tens carry sensing means individual to each accumulator and movable responsive to movement of said accumulator through tens carry position for rocking said detent means in the adjacent higher order to disengage said higher order detent means from its said latch means whereupon said related latch means is free to move to engage with said transverse member, and a blocking means extending transversely in said machine and located in the path of said member-engaging movement of all

25 inboard said latch means for preventing engagement of any said inboard latch means with said transverse members, whereby the first outboard order latch means is the lowest order latch means that can engage with said member when the highest inboard order accumulator is moved through tens carry position, and whereby when any said carry unit is located inboard it is not actuatable to effect carry operations in the respective inboard order even though said adjacent

30 lower order accumulator is moved through tens carry position.

35 13. The construction according to claim 12 wherein each said carry unit comprises a coupler carried by said first lever and movable relative to said first lever into engagement with the adjacent lower order first lever for rotation of the higher order first lever together with said lower order first lever upon rotation of said lower order first lever, and a pre-carry sensing means in each order engaging said coupler of the adjacent higher order and movable for sensing the pre-carry position, adjacent to said tens carry position, of the related said accumulator for thereupon engaging said higher order coupler with

40

the adjacent lower order first lever when said lower order accumulator is standing at said pre-carry position, whereby all carry units so inter-coupled with said first outboard order carry unit are operable to simultaneously effect carry operations in all said inter-coupled orders when said first outboard order first lever is rotated by said transverse members as aforesaid.

14. An outboard carry mechanism for a calculating machine comprising an ordinarily shiftable carriage, a series of ordinal accumulators rotatably mounted on said carriage, successive orders of said accumulators being movable outboard relative to said machine upon shifting of said carriage and all others of said accumulators being inboard relative to said machine, each accumulator being rotatable individually according to digit values in a first direction for additive operations and in the opposite direction for subtractive operations, a plurality of ordinarily disposed accumulator actuators in said machine operable for rotating all inboard orders of said accumulators according to digit values, and an inboard tens carry mechanism for effecting tens carry operations in inboard orders of said accumulators; said outboard carry mechanism being carried by said carriage and comprising similar carry units, one for each order of said accumulators that can be carried outboard; an operating device comprising a movable first transverse member common to and for all said carry units; each carry unit comprising first and second coaxial levers, said second lever being yieldably constrained to rotate together with said first lever until said second lever is stopped whereupon said first lever is movable further angularly relative to said second lever, stop means for said second lever, a pawl means carried by said second lever and movable relative to said second lever from normal additive position to subtractive position, for in each position to engage and rotate the related said accumulator respectively in said first direction and said opposite direction for a tens carry upon rotation of said second lever against said stop means, spring biased latch means carried by said first lever and movable relative to said first lever into engagement with said first transverse member under the influence of said spring bias for subsequent angular movement of said first and second levers by movement of said first transverse member, a rockable detent means contacting said latch means for normally holding said latch means disengaged from said first transverse member, a tens carry sensing means individual to each accumulator and movable responsive to rotation of said accumulator through tens carry position for rocking said detent means in the adjacent higher order to disengage said higher order detent means from its related said latch means whereupon said related latch means is free to move to engage with said first transverse member, and a blocking means extending transversely in said machine and located in the path of said member-engaging movement of all said latch means that are inboard for preventing engagement of any said inboard latch means with said first transverse member when said related detent is disengaged from said inboard latch means, whereby the first outboard order latch means is the lowest order latch means that can engage with said first transverse member when the adjacent inboard order accumulator is rotated through tens carry position.

15. The construction according to claim 14 wherein said stop means in said carry unit orders is a transverse rod mounted on said carriage and common to all said second levers, and each second lever comprises an arm for contacting said transverse rod upon said rotation of said second lever.

16. The construction according to claim 14, and comprising a transverse rod secured on said carriage for and common to all said first levers, a first spring connected to each said first lever and said carriage for yieldably holding said first lever at rest position in contact with said rod, each said first lever carrying a lateral lug, and a second spring connected to said first and second levers for yieldably holding said second lever in contact with said lug for said constraining of said second lever to rotate together with said first lever.

17. The combination according to claim 14 wherein each accumulator comprises a rotatable gear for rotating said accumulator, a transverse rod means common to said carry units, said rod means being normally in additive position and movable to subtractive position, and each said pawl means being pivotally mounted on said second lever and comprising first and second arms engageable with said gear for said movement of said accumulator for tens carry upon said rotation of said second lever, said pawl means also comprising a third arm contacting said rod means for being rocked from additive position to subtractive position by movement of said rod means from its additive position to subtractive position, spring means connected to said pawl means and said second lever for yieldably holding said third arm in said contact with said rod means, so that in said additive position of said pawl means said first arm engages said gear for effecting said tens carry rotation of said accumulator in said first direction and said second arm engages said gear in the final phase of said tens carry operation for blocking over-rotation of said gear upon said rotation of said second lever, and in said subtractive position of said pawl means said second arm engages said gear for effecting tens carry rotation of said accumulator in said opposite direction and said first arm engages said gear in the final phase of said tens carry operation for blocking over-rotation of said gear upon said rotation of said second lever, whereby over-rotation of said outboard accumulators during carry operations therein is prevented.

18. The construction according to claim 14 wherein each said latch means is pivotally mounted on said first lever, a spring connected to said latch means and said first lever for said biasing of said latch means to engage with said first transverse member, said latch means comprising lug means normally contacted by said detent means for said holding of said latch means disengaged from said first transverse member, said latch means also comprising hook means for latching with and being moved by said first transverse member as aforesaid, and comprising an arm projection for contacting said blocking means when said latch means is inboard for preventing engagement of said latch means with said first transverse member as aforesaid, said latch means also comprising a surface portion engageable by said first transverse member for rocking said latch means to re-engage with its said detent means when said latch means is disengaged from said detent means, said first transverse member being normally at rest position engaging all said surface portions and being movable in a first direction to latch-engaging position for engagement therewith of any subsequently freed outboard latch means and being then movable further in said first direction to operated position to actuate any latched first lever for a carry operation in the respective order as aforesaid, whereupon said first transverse member is movable in the opposite direction to engage said surface portion of any said freed latch means for effecting said re-engagement thereof with its detent means.

19. The construction according to claim 14 and including a shaft secured on said carriage, a transverse rod secured on said carriage, each said detent means being pivoted on said shaft, each said tens carry sensing means comprising a lever means pivoted on said shaft and extending adjacent to said accumulator of the respective order, a lateral stud carried by said accumulator, a lateral extension secured to said lever means and formed with a lug projection engaging the said detent means which is in the adjacent higher order, so that actuation of said lever means disengaged said detent means from its latch means, a first spring connected to said lever means and said carriage for yieldably holding said lever means at rest position in contact with said rod, a second spring connected to said detent means and said carriage for holding said detent means normally in contact with said lug projection, said lever means being formed on its distal end with first and second surface portions adjoining each other along a common edge and formed angularly relative to each other, said first surface portion standing in the path of movement of said stud for being moved by said stud when said accumulator is rotated through

tens carry position in additive operations, and said second face standing in the path of movement of said stud for being moved by said stud when said accumulator is rotated through tens carry position in subtractive operations.

20. The combination according to claim 14 and comprising a coupler carried by said first lever and movable relative to said first lever into engagement with the adjacent lower order first lever for rotation of the higher order said first lever together with said adjacent lower order first lever upon said rotation of said lower order first lever, and a pre-carry sensing means in each order engaging said coupler of the adjacent higher order and movable for sensing the pre-carry position, adjacent to said tens carry position, of the related said accumulator in either additive operations or in subtractive operations, for thereupon moving said higher order coupler into engagement with the respective adjacent lower order first lever when said lower order accumulator is standing at said pre-carry position, whereby all carry units so inter-coupled with said first outboard carry unit are operable substantially simultaneously to effect carry operations in all said inter-coupled orders when said first outboard first lever is rotated by said first transverse member, as aforesaid.

21. The construction according to claim 20 wherein a lateral first projection is carried by each said first lever so as to extend toward the adjacent higher order first lever, a said coupler being pivotally mounted on each said adjacent higher order first lever, a lateral second projection formed on each said coupler for contacting said pre-carry sensing means of said adjacent lower order for being movable by said pre-carry sensing means into coupling position in the path of movement of said first projection in the adjacent lower order upon rocking of said coupler in a first direction by said pre-carry sensing means when said lower order accumulator stands at said pre-carry position, said coupler being rockable further in said first direction by said pre-carry sensing means to ineffective position when the related accumulator stands at a position other than said pre-carry position, and a spring connected to said coupler and said first lever for biasing said coupler in the opposite direction to rest position and holding said coupler in said contact with said pre-carry sensing means.

22. The construction according to claim 21 and comprising a guide means for each said coupler for preventing disengagement of the respective first and second projections by blocking any rocking of said coupler during movement of said higher order first lever by the adjacent lower order first lever, whereby loss of an order in a series of inter-coupled orders is prevented during carry operations in the respective orders.

23. The construction according to claim 22 wherein each said guide means comprises a plate secured to said carriage and formed with an opening through which said second projection extends, said opening permitting movement of said second projection from said rest position to said ineffective position by said pre-carry sensing means, and at said coupling position said opening being formed for guided free passage therein of said second projection in its movement by said first projection.

24. The construction according to claim 20 and comprising lug means carried by each accumulator, said actuating means comprising a second transverse member common to all said pre-carry sensing means and movable between rest and operated positions and normally standing at said rest position, a transverse rod means common to all said pre-carry sensing means and movable between additive operation position and subtractive operation position and normally standing at said additive operation position, each said pre-carry sensing means comprising a pivoted third lever having first and second arms, said first arm being contacted by the adjacent higher order coupler, a first spring means coupled to said second transverse member and said third lever for yieldably constraining said third lever to contact its first arm with said second transverse member so that said third lever rotates in response to movement of said second transverse member to said operated position, a sensing member pivoted on a distal portion of said

second arm for engaging said lug means of the related accumulator when said third lever is rotated and said accumulator is at said pre-carry position, said lug means then blocking movement of said third lever at coupling position intermediate rest position and operated position at which coupling position said adjacent higher order coupler is in said engagement with said first lever of the respective lower order, and so that when said accumulator of an order stands at a position other than said pre-carry position said lug means is then out of the path of movement of said sensing member, whereby said third lever moves together with said second transverse member to operated position for moving said adjacent higher order coupler to ineffective position relative to said first lever of the respective adjacent lower order, a stud carried by said sensing member, a fourth lever pivoted on said rod means and formed with a V-shaped notch on a distal portion for engaging said stud in said notch, a second spring means secured to said fourth lever and said rod means for yieldably holding said fourth lever in engagement with said stud, so that movement of said rod means from one to the other of said additive position and subtractive position, moves said sensing member to the respective pre-carry sensing position for said contact with said lug means when said accumulator stands at pre-carry position in additive and subtractive operations.

25. An outboard carry mechanism for a calculating machine comprising an ordinarily shiftable carriage, a series of ordinal accumulators rotatably mounted on said carriage, successive orders of said accumulators being movable outboard relative to said machine upon shifting of said carriage and all others of said accumulators being inboard, each accumulator being rotatable individually according to digit values in a first direction for additive operations and in the opposite direction for subtractive operations, a plurality of ordinarily disposed accumulator actuators in said machine operable for rotating all inboard orders of said accumulators according to digit values, and an inboard tens carry mechanism for effecting tens carry operations in inboard orders of said accumulators; said outboard carry mechanism being carried by said carriage and comprising similar carry units, one carry unit for each order of said accumulators that can be carried outboard; an operating device comprising a movable first transverse member for and common to all said carry units; each carry unit comprising first and second coaxial levers, said second lever being yieldably constrained to rotate together with said first lever until said second lever is stopped whereupon said first lever is movable further angularly relative to said second lever, a stop rod common to all said second levers and engageable by each said second lever for stopping movement of said second lever, a spring biased pawl means pivoted on said second lever and rockable against said spring bias from normal additive position to subtractive position for engaging and rotating the related said accumulator respectively in said first direction and said opposite direction for a tens carry upon rotation of said second lever against said stop rod, a spring biased latch means pivoted on said first lever and rockable under the influence of said spring bias into engagement with said first transverse member for subsequent rotation of said first and related second levers by said first transverse member, a rockable detent means engaging said latch means for normally holding said latch means retracted from engagement with said first transverse member, a tens carry sensing means for each said accumulator and connected to the adjacent higher order detent means, said tens carry sensing means being movably responsive to rotation of said accumulator through tens carry position for rocking said adjacent higher order detent means to disengage from the related said latch means whereupon said latch means is free to rock into said engagement with said first transverse member; a blocking means extending transversely in said machine and standing in the path of said rocking movement of any inboard said latch means so that the first outboard latch means is the lowest order latch means that may rock to engage with said first transverse member when the adjacent inboard order accumulator is rotated through said tens carry

position; said latch means comprising a surface portion contactable by said first transverse member for rocking said latch means to re-engage with its said detent means when said latch means is disengaged from said detent means, said first transverse member being normally at rest position at which position said first transverse member is in engagement with all said surface portions, said first transverse member being movable in a first direction from rest position to latch-engaging position for said engagement therewith of any subsequently freed outboard latch means, and said first transverse member being thereafter movable further in said first direction to operated position for said rotation of any said first lever latched thereto, whereupon said first transverse member is movable in the opposite direction to its said rest position thereby to contact said surface portion of any said freed latch means for effecting said re-engagement thereof with its said detent means, a lateral first extension carried by each of said first levers for movement with its said first lever and extending toward the adjacent higher order first lever, a spring biased coupler pivoted on each said higher order first lever and comprising an integral second extension rockable in a first direction against said spring bias into the path of movement of said first extension so that all first levers successively inter-coupled with the first outboard one of said first levers are rotated substantially simultaneously together with said first outboard first lever when said first outboard order first lever is rotated by said first transverse member as aforesaid; lug means carried by each accumulator; said operating device comprising a second transverse member movable between rest and operated positions and normally standing at its said rest position; a pre-carry sensing means in each order comprising a pivoted third lever having first and second arms, said first arm contacting said second extension of the adjacent higher order coupler for rocking said higher order coupler in said first direction upon rotation of said third lever, said first arm also normally contacting said second transverse member and being spring influenced to rotate in response to movement of said second transverse member to its said operated position, a sensing member pivoted on a distal portion of said second arm for engaging said lug means of the related accumulator when said third lever is rotated and said accumulator is at pre-carry position, adjacent to said tens carry position, said lug means then blocking movement of said third lever at coupling position intermediate rest position and operated position, at which coupling position said adjacent higher order second extension is in coupled relation with said first extension of the respective lower order, and when said accumulator stands at a position other than said pre-carry position said lug means is out of the path of movement of said sensing member so that said third lever moves together with said second transverse member to operated position, thereby rocking said adjacent higher order coupler in said first direction to ineffective position relative to said first lever of the respective lower order; a guide means for each second extension for preventing disengagement of the respective first and second extensions by blocking any rocking of said coupler when said coupler is in coupling position and said related first lever is being rotated therethrough by said adjacent lower order first lever, so that loss of an order in a series of inter-coupled first levers is prevented during carry operations; a stud carried by each said sensing member; a transverse rod means movable between additive position and subtractive position and normally standing at said additive position, spring biased ordinal fourth levers pivoted on said rod means, each fourth lever being formed with a V-shaped notch on a distal portion for engaging with said stud of the respective order under said spring bias so that movement of said rod means from one to the other of said additive position and subtractive position, rocks said sensing member to the respective pre-carry sensing position for said contact with said lug means when said accumulator stands at pre-carry position in additive and subtractive operations, said V-shaped notch permitting temporary displacement of said sensing member by said lug means from normal position relative to said third lever when

the related third lever is at said operated position and the related accumulator is rotated to said pre-carry position during a carry operation of said accumulator.

26. The construction according to claim 25 wherein said operating device comprises first and second shafts, a pair of axially spaced first carrier levers rotatable on said first shaft and each being formed with angularly spaced first and second arms, said first transverse member being secured at each of its ends to one of said second arms for being carried thereby, a pair of axially spaced second carrier levers rotatable on said second shaft, said second transverse member being secured at each of its ends to one of said second carrier levers for being carried thereby, a pair of first actuating levers and a pair of second actuating levers rotatable on said first shaft, each of said second actuating levers being spaced axially from a different one of said first carrier levers toward the respective end of said first shaft, and a said first actuating lever being disposed between each said second actuating lever and the related first carrier lever, a link pivotally connected to each second carrier lever and said second transverse member for angular actuation of said second transverse member upon rotation of said second actuating levers, each said first actuating lever being formed with a lateral projection normally engaging said first arm and having lost motion relative to said second arm of the respective first carrier lever, a journaled shaft, a pair of levers pinned to said shaft, link means connecting each said pinned lever to a different one of said first actuating levers for rotating said first actuating levers in unison upon rotation of said journaled shaft, one of said pinned levers being spring influenced for yieldable holding of said first transverse member at said rest position, means actuated by the main operating means of said machine for rotating said journaled shaft from rest position to operated position against said spring influence subsequent to actuation of said accumulator actuators and said inboard tens carry mechanism, first and second detaining levers rotatable on said first shaft for said first transverse member, a fixed rod, a first spring means secured to said first and second detaining levers for influencing said detaining levers in opposite directions toward each other and against said fixed rod, said first detaining lever normally being in contact with said fixed rod and said second detaining lever being held by said first transverse member displaced from said fixed rod when said first transverse member is at said rest position, so that under the influence of said first spring means said second detaining lever rotates said first transverse member together with said first actuating levers until said second detaining lever is stopped by said fixed rod when said actuating levers are rotated from rest position to operated position, said first transverse member being then temporarily detained at said latch-engaging position by said detaining levers until said lateral projections engage said second arms and rotate said first carrier levers for moving said first transverse member to operated position, said first transverse member then displacing said first detaining lever from said fixed rod against said spring influence, an intermediate lever rotatable on said first shaft between each said first actuating lever and the related said first carrier lever and formed with a lateral lug means normally in contact with the related said second actuating lever so as to be movable in advance of said second actuating lever, a second spring means secured to each said second actuating lever and said related lateral lug means for yieldably influencing said second actuating lever to rotate together with the related intermediate lever, a finger integral with each of said first actuating levers, each said lateral lug means standing in the path of movement of the related said finger, a third spring means secured to each first actuating lever and the related said intermediate lever for influencing said intermediate lever and said related first actuating lever to contact the respective said finger and lateral lug means with each other, said fingers being angularly displaced from said lateral lug means when said first and second transverse members are at their rest positions, so that upon rotation of said first actuating levers to operated position said fingers contact

said lateral lug means when said first transverse member moves into said latch-engaging position, whereupon said fingers move said lateral lug means for rotating said second transverse member to its said operated position while said first transverse member is detained at said latch-engaging position, whereby the operations of moving said first transverse member to latch-engaging position to enable said latching of the first outboard order first lever therewith, of moving said second transverse member to operated position for said intercoupling of successive orders of said first levers with said first outboard first lever, and of moving said first transverse member from said latch-engaging position to operated position for effecting tens carry in said orders including said latched first lever and all first levers inter-coupled therewith, are performed sequentially substantially as set forth.

27. In a calculating machine having an ordinarily shiftable carriage, a register comprising ordinal accumulators carried by said carriage and shiftable ordinarily therewith, and accumulator actuator means having fixed ordinal positions in said machine and being operable for actuating and performing carry operations in the orders of said accumulators that are inboard in engaging relation with said accumulator actuator means; an outboard carry mechanism for performing carry operations in the higher orders of said accumulators that may be outboard in respect to said accumulator actuator means, said outboard carry mechanism comprising carry means carried on said carriage in each outboard order of said accumulators operable for engaging and performing tens carry in its respective accumulator order, outboard carry actuating means operable in sequence following operation of said accumulator actuator means for operating the said carry means that may be connected therewith, outboard carry engaging means in each outboard order of said accumulators responsive to actuation of the next lower order said accumulators through tens carry for connecting the said carry means in its order to said carry actuating means for operation therewith, and blocking means in the inboard orders of said machine for blocking the said outboard carry engaging means, that are moved inboard by the shifting of said carriage, from engagement with said carry actuating means and for thereby preventing operation of the said carry means that are moved inboard.

28. The combination according to claim 27 wherein said outboard carry mechanism further comprises an intercoupling means secured to each said carry means and engageable with the adjacent lower order said carry means for operation of the said carry means in one order with the said carry means of the next lower order, and sensing means in each outboard order of said accumulators operable in sequence following operation of said accumulator actuator means and prior to operation of said outboard carry actuating means for sensing its respective order of said accumulators and upon sensing a pre-carry standing in that order for engaging the next higher order said intercoupling means with the said carry means of the order in which a pre-carry standing is sensed.

29. In a computing device having a multiorder accumulator register, the combination of a plurality of sensing means operable for sensing pre-carry standings in respective order of said register, a first universal means for operating said sensing means, a plurality of carry means operable under control of said sensing means for performing tens carry in respective consecutive orders of said register, a second universal means for operating said carry means, and a carry actuating means operable a first extent for operating said first universal means and operable a second extent for operating said second universal means, whereby said sensing means and said carry means are operated sequentially in that order by one motion of said carry actuating means.

30. A plurality of ordinarily arranged register means operable incrementally for indicating digital numbers; a plurality of carry means, one such carry means for each order of said register means, operable for increasing or reducing respective register means by one increment in additive and subtractive operations, respectively; a plurality of extended carry deter-

mining means, one such determining means for each order of said register means operable for sensing said register and responsive to a pre-carry condition in its respective said register means for coupling the next higher order said carry means for operation together with its respective said carry means; add-subtract computations control means presettable for controlling said carry means and for controlling said determining means to respond to a nine or zero standing in each respective said register means in additive and subtractive operations respectively; computation motivating means comprising a register actuator means for operating at least one of said register means, sensing actuating means for operating said determining means and carry actuating means operable for operating any said carry means that may be connected therewith, said computation motivating means being operable for actuating said register actuator means, said sensing actuating means and said carry actuating means in that sequential order, and initial carry means movable responsive to tens carry in one order of said register means for connecting said carry means in the next higher order for operation with said carry actuating means, whereby all carry means inter-coupled with the said carry means one order above said initial carry means are operated by said carry actuating means.

31. In a calculating machine having multiplying means operable for producing a product of all the digits of a multiplicand and any single value multiplier in the series one to nine, the combination of a plurality of registers some of which registers are disposed inboard for operation directly by said multiplying means and some of which registers are outboard and free from direct operation by said multiplying means, a plurality of tens carry devices independently operable for operating the registers that are outboard to perform tens carry in their respective orders, a plurality of carry indicating elements connected individually to and movable coextensively with respective orders of said registers for indicating a pre-carry standing of its respective said register, a sensing means operable by said multiplying means in sequence following entry of a complete product in said registers for sensing each ordinal carry indicating element and when said element stands at pre-carry for coupling its respective tens carry device for operation with the next adjacent lower order tens carry device, a carry operating device connected with said multiplying means for a single operation in sequence by said multiplying means following the operation of said sensing means for operating any said tens carry devices connected therewith, and a plurality of ordinal tens carry engaging means one of which is connected to each of said tens carry devices and the lowest outboard order of which is operable responsive to tens carry in the highest inboard order of said registers for connecting its respective lowest outboard order said tens carry device with said carry operating device for operation of the connected said tens carry device by said operating device, whereby the lowest outboard order said tens carry device connected with said operating device and all higher orders of said tens carry devices coupled together and with said lowest outboard order said tens carry device are operated simultaneously by a single operation of said operating device.

32. The construction according to claim 31, characterized further in that said multiplying means comprises a blocking means standing in the path of movement of all said engaging means that are shifted inboard below the highest inboard order.

33. A tens carry mechanism for a multiorder register on an ordinarily shiftable carriage in a calculating machine, the highest order of said register always being inboard relative to said machine and the other orders being movable inboard or outboard successively upon shifting of said carriage, the lowest order inboard register order being the first inboard order, each order of said register comprising a rotatable numeral wheel and a gear for rotating said numeral wheel, an actuator in said machine engageable with said first inboard order gear and movable according to digit values for effecting rotation of the related numeral wheel in a first direction in additive

operations and in the opposite direction in subtractive operations, said carry mechanism being mounted inboard said machine and comprising a plurality of ordinally disposed similar carry units, one carry unit for each register order, except the first inboard order, and relative to the inboard position of said register orders, so that the lowest order carry unit is associated with the second inboard order of said register, said carry mechanism also comprising lug means secured to each gear, a stud means secured to each numeral wheel, except the highest order numeral wheel, a spring biased rockable first bellcrank in each register order except said highest order and comprising first and second bellcrank arms, said first bellcrank arm standing in the path of movement of the related said stud means for being rocked against said spring bias by said stud means when the related said numeral wheel is rotated through tens carry position in said first direction or in said opposite direction, a spring biased rockable second bellcrank supported in said machine and comprising third and fourth bellcrank arms, said third bellcrank arm being engageable with said second bellcrank arm in said first inboard order for being rocked against said spring bias by said first bellcrank when the related numeral wheel is rotated through said tens carry position, a first shaft, a second shaft and a stop rod mounted on said machine transverse to said carry units, each said carry unit comprising a spring influenced first lever pivoted on said first shaft and normally at rest position in contact with said stop rod under said spring influence, a first transverse means movable between additive operation position and subtractive operation position and normally standing at said additive operation position, first and second pawls pivoted coaxially on a distal portion of said first lever, a first spring secured to said first and second pawls for yieldably holding said second pawl engaged with said first pawl for rocking of said second pawl in unison with said first pawl relative to said first lever, a latch means pivoted on said first lever between the axis of said lever and of said pawls, a second spring secured to said latch means and said first pawl for holding said first pawl in contact with said first transverse means so that said first and second pawls move together with said first transverse means from additive operation position to subtractive operation position, in said additive position of said pawls said first pawl being engageable with said gear associated therewith for effecting rotation of the related said numeral wheel in said first direction for a tens carry when said first lever is rocked to operated position, in said subtractive position of said pawls said second pawl being engageable with said associated gear for effecting rotation of said related numeral wheel in said opposite direction for a tens carry when said first lever is rocked to said operated position, and in each instance in the final phase of said movement of said first lever to said operated position, the other of said pawls engages said gear for blocking over-rotation of said gear and numeral wheel, a second transverse means normally being at rest position and movable to operated position, a spring biased detent means pivoted on said second shaft and normally engaging said latch means under said spring bias for holding said latch means against the influence of said second spring and retracted from engagement with said second transverse means in rest position, disengagement of a said detent means from its related latch means permitting said latch means to engage with said second transverse means so that movement of said second transverse means to operated position rocks any first lever so latched thereto for effecting a tens carry in the respective register order associated therewith, a lateral extension carried by each said detent means and extending to the adjacent lower order carry unit, and the lowest order detent extension standing in the path of movement of said fourth bellcrank arm for being rocked by said fourth bellcrank arm to disengage from the related said latch means for permitting said latch means to engage said second transverse means when the first inboard order numeral wheel rotates through tens carry position, a pre-carry sensing means in each carry unit order for sensing said lug means associated therewith when said related numeral

wheel stands at pre-carry position, adjacent to said tens carry position, and a lever means movable responsive to said pre-carry sensing means only when said associated numeral wheel stands at said pre-carry position for engaging said detent extension of the adjacent higher order for rocking said higher order detent to disengage from its related said latch means for liberating said latch means to engage with said second transverse means whereby, when said first inboard order numeral wheel rotates through tens carry position and a series of higher order numeral wheels adjacent to said first inboard order stand at pre-carry position, the latch means associated with said second inboard register order and said higher order latch means, associated with said register orders in series and standing at pre-carry position, are all liberated for engagement with said second transverse means for subsequent simultaneous tens carry actuation of the associated register orders.

34. The construction according to claim 33 and comprising a lateral finger integral with each latch means engaging the adjacent lower order latch means so that when said lower order latch means is not liberated to rock into engagement with said second transverse means, due to standing of the associated register order at a position other than said pre-carry position, said higher order latch means is blocked from rocking into engagement with said second transverse means even though the register order associated with said higher order latch means stands at said pre-carry position.

35. The construction according to claim 33 wherein said pre-carry sensing means comprises a second lever pivoted on said first shaft and normally at rest position in contact with said stop rod, a sensing member and a guide member pivoted coaxially on a distal portion of said second lever, said guide member contacting said first transverse means for being rocked relative to said second lever by said first transverse means from additive position to subtractive position, a third spring secured to said guide member and said second lever for holding said guide member in said contact with said first transverse means, a fourth spring secured to said sensing member and said guide member for yieldably holding said sensing member in contact with said guide member for rocking of said sensing member together with said guide member between said additive position and subtractive position for aligning said sensing member for said sensing of said lug means of the associated register order when the related numeral wheel stands respectively at additive pre-carry position and subtractive pre-carry position and said second lever is rotated, said lug means in a pre-carry position then arresting said second lever midway between its said rest position and operated position, but when said lug means stands at a position other than pre-carry position said second lever is unobstructed in its movement to operated position, said lever means being pivotally mounted on said second lever intermediate the axis of said second lever and said distal portion, a lateral lug integral with said lever means and normally engaging said second lever so that said lever means is rockable about its pivot relative to said second lever when said second lever is arrested at said midway position, a fifth spring secured to said stop rod and said lever means for normally holding said lever means in said engagement with said second lever and therethrough holding said second lever in said contact with said stop rod, actuating means engaging said lateral lug for normally angularly moving said lever means about the axis of said second lever against the tension of said fifth spring thereby normally rotating said second lever to operated position, said lever means being free from contact with said lateral extension of the adjacent higher order when said second lever is unobstructed in its movement from rest position to operated position, and so that when said second lever is arrested at said midway position, said actuating means rocks said lever means relative to said second lever whereupon said lever means engages and moves said adjacent higher order detent extension for disengaging said higher order detent means from its said latch means as aforesaid.

36. The construction according to claim 33 wherein said actuator is normally in additive operation position and is rocka-

ble to subtractive operation position to effect said rotation of said first inboard numeral wheel respectively in said first direction and in said opposite direction, said first transverse means comprising a journaled shaft, a pair of axially spaced bail arms secured to said shaft and a bail rod common to and engaging all said first pawls and being secured at its ends to said bail arms for movement of said bail rod between additive and subtractive operation positions upon rocking of said journaled shaft in one direction to additive position and in the opposite direction to subtractive position, and an optionally operable means connected to said actuator and said journaled shaft for moving said actuator and said journaled shaft in unison selectively from one to the other of said additive position and subtractive position.

37. The construction according to claim 33 wherein said first shaft is journaled, and said second transverse means comprises a pair of axially spaced bail arms secured to said first shaft, and a bail rod secured at its ends to said bail arms for being moved angularly upon rocking of said first shaft, said bail rod being for and common to all said latch means for being engageable by any liberated latch means for said tens carry operation in the register order associated with the latch means engaged with said bail rod, as aforesaid, upon angular movement of said bail rod, and means operable subsequent to operation of said actuator for rocking said first shaft.

38. The construction according to claim 35 wherein said second shaft is journaled, and said actuating means comprises an arm secured to said second shaft for and engaging each said lateral lug for said normal movement of said second lever together with said lever means to operated position and for, at times, said rocking of said lever means relative to said second lever, as aforesaid, upon rocking of said second shaft, and means operable subsequent to operation of said actuator for rotating said second shaft.

39. The construction according to claim 35 wherein said first shaft and said second shaft are journaled, and said second transverse means comprises a pair of axially spaced bail arms secured to said first shaft, and a bail secured at its ends to said bail arms for being moved angularly about the axis of said first shaft upon rocking of said first shaft, said bail being for and common to all said latch means for being engageable by any liberated latch means for said tens carry operation in the register order associated with the latch means engaged with said bail upon said angular movement of said bail, said actuating means comprising an arm secured to said second shaft for and engaging each said lateral lug for said normal movement of said second lever together with said lever means to said operated position of said second lever and for, at times, said rocking of said lever means relative to said second lever, as aforesaid, upon rocking of said second shaft, and means for sequentially rocking said second shaft for said sensing of said pre-carry standing of inboard register orders, as aforesaid, and then rocking said first shaft for said tens carry operation in said second inboard order of said register and in all higher register orders in series with said second inboard register orders and standing at pre-carry position, subsequent to rotation of said first inboard register order through tens carry by said actuator therefor.

40. The construction according to claim 39 wherein said means for sequentially rocking said first and second shafts comprises a first lever member secured to said first shaft, a rest position stop and an operated position stop for said first lever member, said first lever member normally contacting said rest position stop, a second lever member secured to said second shaft and comprising a first lateral projection, a third lever member rotatable on said second shaft and normally engaging said first lateral projection, spring means secured to said second lever member and said third lever member for yieldably holding said third lever member in said engagement with said first lateral projection so that said second lever member rocks together with said third lever member, when said third lever member is rotated, a second lateral projection on said third lever member spaced from said first lever

member and engageable therewith upon rotation of said second lever member together with said third lever member sufficiently to effect said liberation of said latch means of any order associated with a register order standing at pre-carry position, whereupon said second projection rocks said first lever member from rest position for effecting said carry operations, as aforesaid, and means operable for rotating said third lever member subsequent to operation of said actuator for said first inboard register order.

41. The construction according to claim 33 and comprising restoring means operable for re-engaging any liberated latch means with its related detent means said restoring means comprising a journaled shaft, axially spaced bail arms secured to said journaled shaft and a rod secured at its ends to said bail arms for being moved angularly about the axis of said journaled shaft upon rocking of said journaled shaft, said rod engaging any said liberated latch means for rocking said latch means to re-engage with its said related detent means upon said angular movement of said rod, and motivating means connected to said journaled shaft and operable subsequent to actuation of said second transverse means for rocking said journaled shaft.

42. A register carry device comprising the combination of a plurality of rotatable register means; a plurality of carry indicators one for and cooperatively associated with each of said register means and rotatable therewith; and carry means comprising a plurality of flexible feelers extendable from an ineffective position toward the axis of said indicators for contacting said carry indicators when a respective said indicator stands at pre-carry position and yieldable upon rotational contact of said indicators against the side of said feelers, and a plurality of carry members for effecting carry in said register means according to and under control of said feelers upon extending contact of said feelers with said indicators for effecting carry in said register means while said feelers remain in their extended position.

43. In a calculating machine, a plurality of ordinarily arranged carry means operable for performing tens carry operations, carry actuating means operable for operating any said carry means connected therewith, an initial carry means responsive to tens carry in a units order for connecting the tens order carry means with said carry actuating means, a plurality of extended carry determining means in the tens order and succeeding orders operable for sensing pre-carry conditions in each respective order and responsive to consecutive precarry conditions for thereupon connecting the next higher order said carry means with said carry actuating means, carry reset means operable from ineffective position to effective position for disconnecting all said carry means from said carry actuating means, and computation motivating means cyclically operable for first operating said reset means into said ineffective position for permitting connection of said carry means with said carry actuating means, second for performing registration operations which may result in tens carry in said units order, third for operating said extended carry determining means, fourth for operating said carry actuating means and fifth for operating said carry reset means into said effective position, whereby all tens carry operations are performed simultaneously and all carry operations are performed by said motivating means.

44. In a register including an ordinal series of register wheels, a reciprocatory transfer actuator for each wheel, a common reciprocatory drive means for said actuators, normally disabled connecting means adjustable upon movement of each wheel from a first to a second given registering position to connect the actuator of the next higher order wheel to said drive means for a forward stroke in a primary transfer operation, said drive means thereupon being operable in a return stroke to control the restoration of said actuator, normally disabled drive transmission means between each pair of adjacent actuators operable during the forward stroke of operation of the lower order actuator of said pair to transmit like movement to the higher order actuator of said pair in a

secondary transfer operation, said drive means thereupon being operable to control the restoration of said pair of actuators simultaneously and each independently in a return stroke, and means operable when each wheel is in said first given registering position to connect the drive transmission means between its actuator and the actuator of the next higher order wheel.

45. In a register including an ordinal series of register wheels, a reciprocatory transfer actuator for each wheel, a common reciprocatory drive means for said actuators normally ineffectively operable in its forward stroke and normally operable in its return stroke to control the return of all of said actuators simultaneously and each independently from their forward stroke position, normally disconnected coupling means for connecting each actuator to said drive means for forward stroke operation therewith in a primary transfer operation, means operable upon movement of each wheel from a first to a second given registering position to connect the coupling means for the actuator of the next higher order wheel, normally disabled drive transmission means operable by each actuator in its forward stroke, and means operable when each wheel is in said first given registering position to enable the drive transmission means to impart forward stroke secondary transfer operation to the next higher order actuator.

46. In a register including an ordinal series of register wheels, a transfer actuator for each wheel each rockable for forward and return stroke operation, a driving bail for said actuators normally ineffective in forward stroke operation to drive said actuators and normally effective in its return stroke to control the return of all of said actuators simultaneously and each independently from their forward stroke positions, normally disconnected coupling means for connecting each actuator to said driving bail for forward stroke operation therewith in a primary transfer operation, means operable upon movement of each wheel from a first to a second given registering position to connect the coupling means for the actuator of the next higher order wheel, normally disabled drive transmission means operable by each actuator in its forward stroke to impart forward stroke secondary transfer operation to the next higher order actuator, and means operable when each wheel is in said first given registering position to enable the drive transmission means to the actuator of the next higher order wheel.

47. The invention according to claim 46 wherein said actuators are mounted on a shaft.

48. In a register including an ordinal series of register wheels, a transfer actuator for each wheel each having an arm extending outwardly therefrom, a bail extending transversely at one side of said arms normally ineffective in forward stroke operation and normally operable in its return stroke to control the simultaneous return of all operated said arms and therefore said actuators from their forward stroke positions, a coupling member adjustably mounted on each of said arms normally out of the path of movement of said bail in its forward stroke operation and adjustable into said path to impart forward stroke primary transfer operation to the associated actuator, means operable upon movement of each wheel from a first to a second given registering position to adjust the coupling member for the actuator of the next higher order wheel into the forward path of movement of said bail, normally disabled drive transmission means operable by each actuator in its forward stroke to impart forward stroke secondary transfer operation to the next higher order actuator, and means operable when each wheel is in said first given registering position to enable the drive transmission means to the actuator of the next higher order wheel.

49. In a register including an ordinal series of register wheels, a reciprocatory transfer actuator for each wheel, a common reciprocatory drive means for said actuators, normally disabled connecting means adjustable upon movement of each wheel from a first to a second given registering position to connect the actuator of the next higher order wheel to

said drive means for a forward stroke in a primary transfer operation, said drive means thereupon being operable in a forward stroke for operating the connected said actuator out of normal position and then being operable in a return stroke for positively assuring that said actuator and connecting means are restored to said normal position, normally disabled drive transmission means between each pair of adjacent actuators operable during the forward stroke of operation of the lower order actuator of said pair to transmit like movement to the higher order actuator of said pair in a secondary transfer operation, said drive means thereupon being operable to positively assure restoration of said pair of actuators simultaneously and each independently at the end of its return stroke, and means operable when each wheel is in said first given registering position to enable the drive transmission means between its actuator and the actuator of the next higher order wheel.

50. In a register including an ordinal series of register wheels, a transfer actuator for each wheel each rockable for forward and return stroke operation, a common reciprocatory driving bail for said actuators normally blocking forward operation of said actuators and normally ineffective in its forward stroke away from said actuators and effective at the end of its return stroke for blocking all of said actuators in normal position, normally disconnected coupling means for connecting each actuator to said driving bail for forward stroke operation therewith in a primary transfer operation, means operable upon movement of each wheel from a first to a second given registering position to connect the coupling means for the actuator of the next higher order wheel, normally disabled drive transmission means operable by each actuator in its forward stroke to impart forward stroke secondary transfer operation to the next higher order actuator, and means operable when each wheel is in said first given registering position to enable the drive transmission means to the actuator of the next higher order wheel.

51. An ordinally arranged series of register wheels, a reciprocatory transfer actuator for each wheel operable from a normal position to an operated position and back to normal position, a detaining means engaging each said actuator for yieldably holding each said actuator in normal position, a common reciprocatory drive means for said actuators normally standing in the path of operation of said actuators and operable out of normal position away from said actuators in a forward stroke and operable back to normal position toward any operated said actuators in a return stroke of operations, and a normally disabled connecting means adjustable upon movement of each wheel from a first to a second given registering position to connect the actuator of the next higher order wheel to said drive means for a forward stroke operation of a thus connected said actuator together with said drive means in a primary transfer operation and thereafter restoration of any operated said actuators to normal position is positively controlled by said drive means.

52. In a register including an ordinally arranged series of register wheels, a pivotal reciprocatory transfer actuator for each wheel comprising a lever arm shiftable in a first direction from a normal position in a forward stroke and shiftable in a second direction from operated position to normal position in a return stroke of operations for imparting like movement to its said actuator, a detaining means engaging each said actuator for yieldably holding each said actuator and its said arm in normal position, a common pivot support shaft for said actuators situated transverse said wheels, a common reciprocatory drive bail means for said actuators comprising a rod transverse said actuators normally blocking forward operation of said arms and therefore said actuators and being normally ineffective in its forward stroke in said first direction away from said arms of said actuators and being effective at the end of its return stroke in said second direction for blocking all of said arms and said actuators in normal position, normally disconnected hook means pivotally mounted on each said arm and being shiftable from ineffective position to rod engaging posi-

tion for connecting each said arm to said rod for forward stroke operation of said actuator therewith in a primary transfer operation, and means operable upon movement of each wheel from a first to a second given registering position to shift the said hook means for the actuator of the next higher order wheel into engagement with said rod.

5

53. The combination according to claim 52 wherein said drive bail means includes bail portions secured to said rod and mounted on said shaft for arcuate reciprocation of said rod about the axis of said shaft, said arms and said actuators.
